ABSTRACT

Torque that is requested of a motor to generate an experienced inertia different from a mechanical inertia of an actuator is adjusted, wherein the experienced inertia is a flywheel inertia model. In one embodiment, the motor provides resistance to the actuator. In one embodiment, the actuator is coupled to the motor.

**FLYWHEEL MODE FOR DIGITAL
EXERCISE DEVICE**

**CROSS REFERENCE TO OTHER
APPLICATIONS**

This application claims priority to U.S. Provisional Patent Application No. 63/645,047 entitled FLYWHEEL MODE AND DROP SET MODE filed May 9, 2024 which is incorporated herein by reference for all purposes.

BACKGROUND OF THE INVENTION

Strength training, also referred to as resistance training or weight lifting, is an important part of any exercise routine. It promotes the building of muscle, the burning of fat, and improvement of a number of metabolic factors including insulin sensitivity and lipid levels. Aerobic training is also important as it promotes endurance and cardiovascular/respiratory health. As referred to herein, exercise training is strength training, aerobic training, or any combination that uses an exercise device.

A digital exercise device is an improvement over a traditional exercise device as it provides a more safe, effective, and engaging experience. Improving a digital exercise device experience to be more efficient and/or provide greater diversity of motion experiences is useful.

BRIEF DESCRIPTION OF THE DRAWINGS

Various embodiments of the invention are disclosed in the following detailed description and the accompanying drawings.

FIG. 1A is a block diagram illustrating an embodiment of an exercise machine capable of digital exercise training.

FIG. 1B illustrates a front view of one embodiment of an exercise machine.

FIG. 2 includes front perspective views of an embodiment of a weight training machine.

FIG. 3 is a diagram illustrating an example of a low speed and high weight mode for the differential.

FIG. 4 is a diagram illustrating a power sharing mode example.

FIG. 5A is a diagram illustrating a concentric phase drivetrain energy flow.

FIG. 5B is a diagram illustrating an eccentric phase drivetrain energy flow.

FIG. 6 is a diagram illustrating an example concentric boost mode for a digital exercise machine.

FIGS. 7A, 7B(1), and 7(2) are diagrams illustrating an example of two different exercise devices with different drivetrain designs.

FIG. 8 is a diagram illustrating the traditional four modes of a motor.

FIG. 9 is a graphical illustration of a control loop for inwards slack control.

FIG. 10 is an illustration of an example of a flywheel mode.

FIG. 11A is a graphical illustration of a control loop for flywheel mode slack control.

FIG. 11B is a graphical illustration of a control loop for flywheel mode slack control using the chains approach.

FIG. 12 is a flow diagram illustrating an embodiment of a process for flywheel mode.

FIG. 13 is a flow diagram illustrating an embodiment of a process for drop set mode.

2
DETAILED DESCRIPTION

The invention can be implemented in numerous ways, including as a process; an apparatus; a system; a composition of matter; a computer program product embodied on a computer readable storage medium; and/or a processor, such as a processor configured to execute instructions stored on and/or provided by a memory coupled to the processor. In this specification, these implementations, or any other form that the invention may take, may be referred to as techniques. In general, the order of the steps of disclosed processes may be altered within the scope of the invention. Unless stated otherwise, a component such as a processor or a memory described as being configured to perform a task may be implemented as a general component that is temporarily configured to perform the task at a given time or a specific component that is manufactured to perform the task. As used herein, the term 'processor' refers to one or more devices, circuits, and/or processing cores configured to process data, such as computer program instructions.

A detailed description of one or more embodiments of the invention is provided below along with accompanying figures that illustrate the principles of the invention. The invention is described in connection with such embodiments, but the invention is not limited to any embodiment. The scope of the invention is limited only by the claims and the invention encompasses numerous alternatives, modifications and equivalents. Numerous specific details are set forth in the following description in order to provide a thorough understanding of the invention. These details are provided for the purpose of example and the invention may be practiced according to the claims without some or all of these specific details. For the purpose of clarity, technical material that is known in the technical fields related to the invention has not been described in detail so that the invention is not unnecessarily obscured.

Adjusting inertia that a user experiences via dynamic torque control for a digital exercise device is disclosed. A digital exercise device as referred to herein is an exercise device wherein electricity is used to generate tension/resistance, for example using an electromagnetic field. In one embodiment, the electromagnetic field is provided via an electronic motor, such as a three-phase permanent magnet synchronous motor (PMSM). An advantage of a digital exercise device over a traditional exercise device is that the digital exercise device may be smaller and lighter than a traditional exercise device such as a weight stack. A digital exercise device may also be more versatile by way of electronic and/or digital control. Electronic control enables the use of a processor/controller to apply tension. By contrast, a traditional exercise device require tension to be changed physically/manually; in the case of a weight stack, a pin has to be moved by a user from one metal plate to another.

A digital exercise device is also versatile by way of using dynamic resistance referred to herein as the ability to change tension/resistance nearly instantaneously and without physical/manual adjustment. When tension is coupled to position of a user against their range of motion, the digital exercise device may apply arbitrary applied tension curves, both in terms of position and in terms of phase of an exercise movement: concentric, eccentric, isometric, and/or aerobic. Furthermore, the shape of these curves may be changed continuously and/or in response to events; the tension may be controlled continuously as a function of a number of internal and external variables including position and phase,

and the resulting applied tension curve may be pre-determined and/or adjusted continuously in real time.

In one embodiment, a digital exercise device emulates a skier and/or rowing ergometer and/or spin bike to provide aerobic exercise to a user. In a traditional skier/rowing machine, a flywheel is used to emulate actual skiing or rowing wherein a fan is suspended in air and/or a fluid with a clutch, and a cable that a user pulls via an actuator engages the drive to drive the fan. When the user stops pulling the clutch disengages and the fan spins with momentum, eventually spinning down on its own. Thus, the user provides a force which exceeds the angular velocity of the rotating of the fan in order to be able to accelerate it up, and the rate in which it accelerates depends on the fan behavior and the fluids in the fan. In one sense, the faster the fan goes, the faster the fan decays down and the more air/fluid the fan has to move. In one embodiment, a digital exercise device emulating a skier and/or rowing ergometer and/or spin bike includes an emulation of a flywheel, and is referred to herein as flywheel mode.

An improvement of flywheel mode is that it allows a digital strength training/exercise device to address blended strength and high intensity interval training (HIIT) workouts to provide improved cardiovascular health for a user. In one embodiment, a state space model is used to translate input force and speed into a flywheel's state variables such as position and velocity. The user's input force and speed update the state space model and then adjust a speed controller that dynamically changes the load applied to the user based on the model's state. The drag factors of fluid such as in rowing ergometers, and/or mass such as in a spin bike, may also be modeled. Using a controller to provide a flywheel inertia model is disclosed. As referred to herein, a flywheel inertia model comprises: a modeling of a flywheel; drag factors such as fluid, fan/propeller behavior, and/or spin bike mass; clutch behavior; and/or decay factors.

In one embodiment, range of motion of the actuator, such as an ergometer handle that the user pulls, is used to adjust torque to generate an experienced inertia different from a mechanical inertia of the actuator and/or a cable coupled between actuator and the digital exercise device, wherein the experienced inertia is a flywheel inertia model. Adjusting torque may comprise reducing slack on the cable as a function of range of motion, for example by applying a slack impulse wave to the digital exercise device. In one embodiment, the exercise device comprises a storage device configured to store the range of motion of the actuator for a repetition ("rep") of an exercise movement for a user.

FIG. 1A is a block diagram illustrating an embodiment of an exercise machine capable of digital exercise training. The exercise machine may include the following, including optional components as not all these elements are necessary:

a controller circuit (104), for example a torque controller (104), which may include a processor, inverter, pulse-width-modulator, and/or a Variable Frequency Drive (VFD);

a motor (106), for example a three-phase AC driven by the controller circuit;

a spool with a cable (108) wrapped around the spool and coupled to the spool. On the other end of the cable an actuator/handle (110) is coupled in order for a user to grip and pull on. The spool is coupled to the motor (106) either directly or via a shaft/belt/chain/gear mechanism. Throughout this specification, a spool may be also referred to as a "hub";

a processor (102), for example a filter (102), to digitally control the controller circuit (104) based on receiving information from the cable (108) and/or actuator (110); optionally (not shown in FIG. 1) a gearbox between the motor and spool. Gearboxes multiply torque and/or friction, divide speed, and/or split power to multiple spools. Without changing the fundamentals of digital exercise training, a number of combinations of motor and gearbox may be used to achieve the same end result. A cable-pulley system may be used in place of a gearbox, a differential gearbox may be used as a gearbox, and/or a dual motor may be used in place of a gearbox;

one or more of the following sensors (not shown in FIG.

1): a position encoder; a sensor to measure position of the actuator (110). Examples of position encoders include a hall effect shaft encoder, grey-code encoder on the motor/spool/cable (108), an accelerometer in the actuator/handle (110), optical sensors, position measurement sensors/methods built directly into the motor (106), and/or optical encoders. In one embodiment, an optical encoder is used with an encoding pattern that uses phase to determine direction associated with the low resolution encoder. Other options that measure back-EMF (back electromagnetic force) from the motor (106) in order to calculate position also exist; one or more sensors to measure voltage and/or current being consumed by the motor (106), for example to provide inputs to calculate electrical power; a user tension sensor; a torque/tension/strain sensor and/or gauge to measure how much tension/force is being applied to the actuator (110) by the user. In one embodiment, a tension sensor is built into the cable (108). Alternatively, a strain gauge is built into the motor mount holding the motor (106). As the user pulls on the actuator (110), this translates into strain on the motor mount which is measured using a strain gauge in a Wheatstone bridge configuration. In another embodiment, the cable (108) is guided through a pulley coupled to a load cell. In another embodiment, a belt coupling the motor (106) and cable spool or gearbox (108) is guided through a pulley coupled to a load cell. In another embodiment, the resistance generated by the motor (106) is characterized based on the voltage, current, or frequency input to the motor.

In one embodiment, a three-phase AC motor (106) is used with the following:

a controller circuit (104)/torque controller (104) combined with processor (102) comprising:

a processor that runs software instructions; three pulse width modulators (PWMs), each with two channels, modulated at 20 kHz; six transistors of a three leg inverter coupled to the three PWMs;

optionally, two or three ADCs (Analog to Digital Converters) monitoring current through each inverter; and/or

optionally, two or three ADCs monitoring inverter phase voltage;

the three-phase AC motor (106), which may include a synchronous-type and/or asynchronous-type permanent magnet motor, such that:

the motor (106) may be in an "out-runner configuration" as described below;

the motor (106) may have a maximum torque output of at least 60 Nm and a maximum speed of at least 300 RPMs;

optionally, with an encoder or other method to measure motor position;

a cable (108) wrapped around the body of the motor (106)

such that the entire motor (106) rotates, so the body of the motor is being used as a cable spool in one case. Thus, the motor (106) is directly coupled to a cable (108) spool. In one embodiment, the motor (106) is coupled to a cable spool via a shaft, gearbox, belt, and/or chain, allowing the diameter of the motor (106) and the diameter of the spool to be independent, as well as introducing a stage to add a set-up or step-down ratio if desired. Alternatively, the motor (106) is coupled to two spools with an apparatus in between to split or share the power between those two spools. Such an apparatus could include a differential gearbox, or a pulley configuration; and/or

an actuator (110) such as a handle, a bar, a strap, or other accessory connected directly, indirectly, or via a connector such as a carabiner to the cable (108).

In some embodiments, the controller (102)/(104) is programmed to drive the motor in a direction such that it draws the cable (108) towards the motor (106). The user pulls on the actuator (110) coupled to cable (108) against the direction of pull of the motor (106).

One purpose of this setup is to provide an experience to a user similar to using a traditional cable-based strength training machine or traditional cable-based aerobic machine like a rower/ergometer, where the cable is attached to a weight stack being acted on by gravity or flywheel. Rather than the user resisting the pull of gravity or flywheel resistance, they are instead resisting the pull of the motor (106).

Taking the example of a strength training device without limitation, note that with a traditional cable-based strength training machine, a weight stack may be moving in two directions: away from the ground or towards the ground. When a user pulls with sufficient tension, the weight stack rises, and as that user reduces tension, gravity overpowers the user and the weight stack returns to the ground.

By contrast in a digital strength trainer, there is no actual weight stack. The notion of the weight stack is one modeled by the system. The physical embodiment is an actuator (110)

motor (106). Thus, note a distinction between the direction the motor (106) is pulling, and the direction the motor (106) is actually turning.

If the controller (102)/(104) is set to drive the motor (106) with, for example, a constant torque in the direction that spools the cable, corresponding to the same direction as a weight stack being pulled towards the ground, then this translates to a specific force/tension on the cable (108) and actuator (110). Calling this force “Target Tension”, this force may be calculated as a function of torque multiplied by the radius of the spool that the cable (108) is wrapped around, accounting for any additional stages such as gear boxes or belts that may affect the relationship between cable tension and torque. If a user pulls on the actuator (110) with more force than the Target Tension, then that user overcomes the motor (106) and the cable (108) unspools moving towards that user, being the virtual equivalent of the weight stack rising. However, if that user applies less tension than the Target Tension, then the motor (106) overcomes the user and the cable (108) spools onto and moves towards the motor (106), being the virtual equivalent of the weight stack returning.

AC Motor. While many motors exist that run in thousands of revolutions per second, an application such as a digital exercise device has different requirements and is by comparison a low speed, high torque type application suitable for an AC motor.

In one embodiment, a requirement of such a motor (106) is that a cable (108) wrapped around a spool of a given diameter, directly coupled to a motor (106), behaves like a 200 lbs weight stack, with the user pulling the cable at a maximum linear speed of 62 inches per second. A number of motor parameters may be calculated based on the diameter of the spool.

User Requirements

Target Weight	200	lbs			
Target Speed	62	inches/sec	=	1.5748	meters/sec

Requirements by Spool Size

Diameter (inches)	3	5	6	7	8	9
RPM	394.7159	236.82954	197.35795	169.1639572	148.0184625	131.5719667
Torque (Nm)	67.79	112.9833333	135.58	158.1766667	180.7733333	203.37
Circumference (inches)	9.4245	15.7075	18.849	21.9905	25.132	28.2735

---

coupled to a cable (108) coupled to a motor (106). A “weight moving” is instead translated into a motor rotating. As the circumference of the spool is known and how fast it is rotating is known, the linear motion of the cable may be calculated to provide an equivalency to the linear motion of a weight stack. Each rotation of the spool equals a linear motion of one circumference or $2\pi r$ for radius r . Likewise, torque of the motor (106) may be converted into linear force by multiplying it by radius r .

If the virtual/perceived “weight stack” is moving away from the ground, motor (106) rotates in one direction. If the “weight stack” is moving towards the ground, motor (106) rotates in the opposite direction. Note that the motor (106) is pulling towards the cable (108) onto the spool. If the cable (108) is unspooling, it is because a user has overpowered the

55 Thus, a motor with 67.79 Nm of force and a top speed of 395 RPM, coupled to a spool with a 3 inch diameter meets these requirements. 395 RPM is slower than most motors available, and 68 Nm is more torque than most motors on the market as well.

Hub motors are three-phase permanent magnet AC direct drive motors in an “out-runner” configuration: throughout this specification out-runner means that the permanent magnets are placed outside the stator rather than inside, as opposed to many motors which have a permanent magnet rotor placed on the inside of the stator as they are designed more for speed than for torque. Out-runners have the magnets on the outside, allowing for a larger magnet and pole count and are designed for torque over speed. Another way

to describe an out-runner configuration is when the shaft is fixed and the body of the motor rotates.

Hub motors also tend to be “pancake style”. As described herein, pancake motors are higher in diameter and lower in depth than most motors. Pancake style motors are advantageous for a wall mount, subfloor mount, and/or floor mount application where maintaining a low depth is desirable, such as a piece of fitness equipment to be mounted in a consumer's home or in an exercise facility/area. As described herein, a pancake motor is a motor that has a diameter higher than twice its depth. As described herein, a pancake motor is between 15 and 60 centimeters in diameter, for example 22 centimeters in diameter, with a depth between 6 and 15 centimeters, for example a depth of 6.7 centimeters.

Motors may also be “direct drive”, meaning that the motor does not incorporate or require a gear box stage. Many motors are inherently high speed low torque but incorporate an internal gearbox to gear down the motor to a lower speed with higher torque and may be called gear motors. Direct drive motors may be explicitly called as such to indicate that they are not gear motors.

If a motor does not exactly meet the requirements illustrated in the table above, the ratio between speed and torque may be adjusted by using gears or belts to adjust. A motor coupled to a 9" sprocket, coupled via a belt to a spool coupled to a 4.5" sprocket doubles the speed and halves the torque of the motor. Alternatively, a 2:1 gear ratio may be used to accomplish the same thing. Likewise, the diameter of the spool may be adjusted to accomplish the same.

Alternatively, a motor with 100 $\times$ the speed and 100 $\times$ the torque may also be used with a 100:1 gearbox. As such a gearbox also multiplies the friction and/or motor inertia by 100 $\times$, torque control schemes become challenging to design for exercise applications. Friction may then dominate what a user experiences. In other applications friction may be present, but is low enough that it is compensated for, but when it becomes dominant, it is difficult to control for. For these reasons, direct control of motor speed and/or motor position as with AC motors is more appropriate for exercise devices.

FIG. 1B illustrates a front view of one embodiment of an exercise machine. In some embodiments, exercise machine (B1000) of FIG. 1B is an example or alternate view of the exercise machine of FIG. 1A. In this example, exercise machine (B1000) includes a pancake motor (B100), a torque controller coupled to the pancake motor, and a high resolution encoder coupled to the pancake motor (B102). As used herein, a “high resolution” encoder refers to an encoder with an electrical angle resolution of 30 degrees or less. In this example, two cables (B503) and (B501) are coupled respectively to actuators (B800) and (B801) on one end of the cables. The two cables (B503) and (B501) are coupled directly or indirectly on the opposite end to the motor (B100). While an induction motor may be used for motor (B100), a PMSM motor may also be used for its cost, size, weight, and performance. In some embodiments, a high resolution encoder assists the system to determine the position of the PMSM motor to control torque. While an example involving a single motor is shown, the exercise machine may include other configurations of motors, such as dual motors, with each cable coupled to a respective motor.

Sliders (B401) and (B403) may be respectively used to guide the cable (B503) and (B501) respectively along rails (B405) and (B407). The exercise machine in FIG. 1B translates motor torque into cable tension. As a user pulls on actuators (B800) and/or (B801), the machine creates/maintains tension on cable (B503) and/or (B501). The actuators

(B800), (B801) and/or cables (B503), (B501) may be actuated in tandem or independently of one another.

In one embodiment, electronics bay (B720) is included and has the necessary electronics to drive the system. In one embodiment, fan tray (B505) is included and has fans that cool the electronics bay (B720) and/or motor (B100).

Drivetrain. As shown in FIG. 1B, the drivetrain is marked by a dash-dot line. As referred to herein, a drivetrain comprises the components that deliver mechanical power between motor (B100) and actuator(s) (B800)/(B801). The drivetrain also comprises the motor itself (B100), the controller (104) in FIG. 1A, and electrical components such as an electrical shunt to dissipate power as heat, and the electrical power supply, typically a wall supply of 120V/240V (not shown in FIG. 1A or 1B). Motor (B100) is coupled by belt (B104) to an optional optical rotary encoder (B102), an optional belt tensioner (B103), and a spool assembly (B200). In one embodiment, an encoder is located in the motor (B100) and element (B102) is not necessary. In one embodiment, the belt tensioner (B103) is not necessary. In one embodiment, motor (B100) is an out-runner, such that the shaft is fixed and the motor body rotates around that shaft. In one embodiment, motor (B100) generates torque in the counter-clockwise direction facing the machine, as in the example in FIG. 1B. Motor (B100) has teeth compatible with the belt integrated into the body of the motor along the outer circumference. Referencing an orientation viewing the front of the system, the left side of the belt (B104) is under tension, while the right side of the belt is slack. The belt tensioner (B103) takes up any slack in the belt. An optical rotary encoder (B102) coupled to the tensioned side of the belt (B104) captures all motor movement, with significant accuracy because of the belt tension. In one embodiment, the optical rotary encoder (B102) is a high resolution encoder. In one embodiment, a toothed belt (B104) is used to reduce belt slip. The spools rotate counter-clockwise as they are spooling cable/taking cable in, and clockwise as they are unspooling/releasing cable out.

Spool assembly (B200) comprises a front spool (B203), rear spool (B205), and belt sprocket (B201). The spool assembly (B200) couples the belt (B104) to the belt sprocket (B201), and couples the two cables (B503) and (B501) respectively with spools (B205) and (B203). Each of these components is part of a low profile design. In one embodiment, a dual motor configuration not shown in FIG. 1B is used to drive each cable (B503) and (B501). In the example shown in FIG. 1B, a single motor (B100) is used as a single source of tension, with a plurality of gears configured as a differential are used to allow the two cables/actuators to be operated independently or in tandem. In one embodiment, spools (B205) and (B203) are directly adjacent to sprocket (B201), thereby minimizing the profile of the machine in FIG. 1B.

As shown in FIG. 1B, two arms (B700), (B702), two cables (B503), (B501) and two spools (B205), (B203) are useful for users with two hands, and the principles disclosed without limitation may be extended to three, four, or more arms (B700) for quadrupeds and/or group exercise. In one embodiment, the plurality of cables (B503), (B501) and spools (B205), (B203) are driven by one sprocket (B201), one belt (B104), and one motor (B100), and so the machine (B1000) combines the pairs of devices associated with each user hand into a single device. In other embodiments, each arm is associated with its own motor and spool. In one embodiment, more than one motor (B100) is coupled to a drivetrain for one or more actuators (B800), for example two

motors (B100) each coupled via a drivetrain similar to that shown in FIG. 1B to a single actuator (B800).

In one embodiment, motor (B100) provides constant tension on cables (B503) and (B501) despite the fact that each of cables (B503) and (B501) may move at different speeds. For example, some physical exercises may require use of only one cable at a time. For another example, a user may be stronger on one side of their body than another side, causing differential speed of movement between cables (B503) and (B501). In one embodiment, a device combining dual cables (B503) and (B501) for a single belt (B104) and sprocket (B201) retains a low profile, in order to maintain the compact nature of the machine, which can be mounted on a wall.

In one embodiment, pancake style motor(s) (B100), sprocket(s) (B201), and spools (B205, 203) are manufactured and arranged in such a way that they physically fit together within the same space, thereby maximizing functionality while maintaining a low profile.

As shown in FIG. 1B, spools (B205) and (B203) are respectively coupled to cables (B503) and (B501) that are wrapped around the spools. The cables (B503) and (B501) route through the system to actuators (B800) and (B801), respectively.

The cables (B503) and (B501) are respectively positioned in part by the use of “arms” (B700) and (B702). The arms (B700) and (B702) provide a framework for which pulleys and/or pivot points may be positioned. The base of arm (B700) is at arm slider (B401) and the base of arm (B702) is at arm slider (B403).

The cable (B503) for a left arm (B700) is attached at one end to actuator (B800). The cable routes via arm slider (B401) where it engages a pulley as it changes direction, then routes along the axis of rotation of track (B405). At the top of rail/track (B405), fixed to the frame rather than the track, is pulley (B303) that orients the cable in the direction of pulley (B300), that further orients the cable (B503) in the direction of spool (B205), wherein the cable (B503) is wound around spool (B205) and attached to spool (B205) at the other end.

Similarly, the cable (B501) for a right arm (B702) is attached at one end to actuator (B801). The cable (B501) routes via slider (B403) where it engages a pulley as it changes direction, then routes along the axis of rotation of rail/track (B407). At the top of the rail/track (B407), fixed to the frame rather than the track is pulley (B305) that orients the cable in the direction of pulley (B301), that further orients the cable in the direction of spool (B203), wherein the cable (B501) is wound around spool (B203) and attached to spool (B203) at the other end.

One use of pulleys (B300), (B301) is that they permit the respective cables (B503), (B501) to engage respective spools (B205), (B203) “straight on” rather than at an angle, wherein “straight on” references being within the plane perpendicular to the axis of rotation of the given spool. If the given cable were engaged at an angle, that cable may bunch up on one side of the given spool rather than being distributed evenly along the given spool.

In the example shown in FIG. 1B, pulley (B301) is lower than pulley (B300). This demonstrates the flexibility of routing cables. In one embodiment, mounting pulley (B301) leaves clearance for certain design aesthetic elements that make the machine appear to be thinner.

In one embodiment, the exercise machine/appliance passes a load/resistance against the user via one or more lines/cables, to a grip(s) (examples of an actuator) that a user displaces to exercise. A grip may be positioned relative to

the user using a load arm and the load path to the user may be steered using pulleys at the load arm ends, as described above. The load arm may be connected to a frame of the exercise machine using a carriage that moves within a track that may be affixed to the main part of the frame. In one embodiment, the frame is firmly attached to a rigid structure such as a wall. In some embodiments, the frame is not mounted directly to the wall. Instead, a wall bracket is first mounted to the wall, and the frame is attached to the wall bracket. In other embodiments, the exercise machine is mounted to the floor. The exercise machine may be mounted to both the floor and the wall for increased stability. In other embodiments, the exercise machine is a freestanding device.

In some embodiments, the exercise machine includes a media controller and/or processor, which monitors/measures user performance (for example, using the one or more sensors described above), and determines loads to be applied to the user’s efforts in the resistance unit (e.g., motor described above). Without limitation, the media controller and processor may be separate control units or combined in a single package. In some embodiments, the controller is further coupled to a display/auditory channel that allows instructional information to be presented to a user and with which the user interacts in a visual manner, which includes communication based on the eye such as video and/or text or icons, and/or an auditory manner, which includes communication based on the ear such as verbal speech, text-to-speech synthesis, and/or music. Collocated with an information channel is a data channel that passes control program information to the processor which generates, for example, exercise loading schedules. In some embodiments, the display is embedded or incorporated into the exercise machine, but need not be (e.g., the display or screen may be separate from the exercise machine, and may be part of a separate device such as a smartphone, tablet, laptop, etc. that may be communicatively coupled (e.g., either in a wired or wireless manner) to the exercise machine). In one embodiment, the display is a large format, surround screen representing a virtual reality/alternate reality environment to the user; a virtual reality and/or alternate reality presentation may also be made using a headset. The display may be oriented in landscape or portrait.

In one embodiment, the appliance media controller provides audio information that is related to the visual information from a program store/repository that may be coupled to external devices or transducers to provide the user with an auditory experience that matches the visual experience. Control instructions that set the operational parameters of the resistance unit for controlling the load or resistance for the user may be embedded with the user information so that the media package includes information usable by the controller to run the machine. In this way a user may choose an exercise regime and may be provided with cues, visual and auditory as appropriate, that allow, for example, the actions of a personal trainer to be emulated. The controller may further emulate the actions of a trainer using an expert system and thus exhibit artificial intelligence. The user may better form a relationship with the emulated coach or trainer, and this relationship may be encouraged by using emotional/mood cues whose effect may be quantified based on performance metrics gleaned from exercise records that track user performance in a feedback loop using, for example, the sensor(s) described above.

Multi-Motor and/or Multi-Spool Based Embodiments

FIG. 2 includes front perspective views of an embodiment of a weight training machine. In one embodiment, the

11

machine of FIG. 2 is the exercise device represented in a block diagram in FIG. 1. In the example of FIG. 2, the exercise device has two arms.

FIG. 2 illustrates an exercise machine with the arms (202) and (204) in a stowed position, where the arms are upright in stowed position (200a). FIG. 2 also shows two other positions: first where the exercise machine with the arms vertically pivoted outwards, or angled away from the body of the exercise machine, pointing in an upwards direction (200b), and second where the arms are in mid-vertical pivot, pointing in a downwards direction (200c).

In this example, control (216) includes controls for unlocking the adjustment of the position of arm (202). In one embodiment, arm (204) also includes a corresponding set of controls. The arms may be independently pivoted to any angle as appropriate.

The exercise machine of FIG. 2 is an embodiment of a digital exercise device/trainer that may use one or two motors as load elements to provide electronic resistance. In the case of a single motor, a differential gearbox may be used. One or two spools may be used with the one or two motors.

In one embodiment, cables travel within the arms, where one end of a cable in a given arm is coupled or otherwise connected to a motor, which may be in the body of the exercise machine. In one embodiment, at the distal end of an arm, away from the body/central console (206) of the trainer, is a handle attached to one end of the cable. A handle is but one example of an actuator that may be used by a user to perform exercise.

In one embodiment, the exercise machine is mounted to a wall. In one embodiment, the exercise machine is floor mounted. The exercise machine may also be a combination of wall/floor mounted. For example, the exercise machine may be mounted to the wall as well as bolted to the floor. The exercise machine may also stand on the floor while being wall mounted. In one embodiment, the exercise machine is freestanding. For example, the exercise machine is attached to a moveable stand, where the stand need not be hard mounted.

In one embodiment, the exercise machine includes one or more of: an antenna, a camera, other optical sensors, depth sensors, infrared sensors, a display, a touch screen, a touch screen controller, an audio input device, a microphone, an audio output device, a speaker, a motor controller, one or more electric motors, one or more spools, one or more cables, and actuators such as handles. The body (206) may include a screen (208).

The motor controller, the handles, and the electric motor are exemplary controllers, exercising components/actuators, and resistive devices/load elements, respectively. In one embodiment, the exercise machine includes multiple motors, for example one per arm. The machine shown in FIG. 2 may have two motors/spools, where an embodiment of a four arm exercise machine (not shown) may have four motors/spools.

In one embodiment, the exercise machine includes a central console (206) for controlling the exercise machine. The console may include a display (208). In one embodiment, the display is a touch screen. In such an example, the display allows instructional information such as virtual training content to be presented to the user and with which a user interacts. In one embodiment, to reduce the interference with an exercise routine that occurs whenever a user interacts with the exercise appliance/machine features or controls, controls are incorporated in the handle. For example, this is an improvement from a case where the user

12

has to release one of the handles in order to use that hand to modify settings selected from options indicated at the display (208) or physical controls located at the control panel (206). Thus, by suitable location of the user controls and application of control context information, the user is able to alter the exercise machine settings with better efficiency to the exercise regime and/or better user safety.

In one embodiment, the exercise machine does not have a display and may be connected to a television or touch-screen monitor via a connection such as HDMI, USB, HDCP, and/or Displayport. In one embodiment, images, video, streaming, audiovisual content, and/or multimedia are transmitted wirelessly to an external display device or other receiver devices such as virtual reality sets, augmented reality sets, set top boxes, and/or game consoles. In one embodiment, data is sent to an application on a mobile device such as a tablet or smartphone, where the application then interprets and renders a user interface for interacting with the exercise machine and/or viewing exercise data measured by the exercise machine for example.

The arms of the exercise machine may have various degrees of freedom (DOFs). In the examples of FIG. 2, the arms of the exercise machine are each capable of moving in at least two directions: 1) horizontal pivot; and 2) vertical pivot (a rotation of the arm relative to the ground). As shown in the example of FIG. 2, the arms pivot vertically about points (212) and (214), which are also referred to herein as the "shoulders" of the exercise machine. In one embodiment, the arms of the exercise machine are each capable of moving in a third direction: translation such as sliding vertically up and down a track.

In one embodiment, the arms of the exercise machine may each have one, two, or three degrees of freedom: 1) vertical pivot, also referred to herein as arm vertical pivoting in the "sagittal" plane, 2) horizontal pivot, to rotate around the shoulder, and/or 3) telescoping of the arm, such as retraction/collapsing of the arm and extension of the arm.

In one embodiment, the arms of the exercise machine are angled outwards from the body (206) of the machine. For example, the arms (202, 204) are not, when extended, perpendicular to the body (206), but rather are slanted horizontally outwards. In one embodiment, angled arms are used in lieu of having an additional degree of freedom, for example, horizontal pivot of the arms, so the arms (202, 204) have two degrees of freedom with vertical pivot and telescoping.

By having the arms on a horizontal pivot angle, when the arms pivot, they start when pointed upward in their most compact/least wide configuration, and widen as they move downwards. This allows the distance between the arms to vary based on the pivot angle. The telescoping, along with the vertical pivot and angled out arms, allows for the arms to provide a large range of motion. The use of angled arms provides various benefits, for example, by simplifying the design of the arms and reducing complexity and cost, such as by removing the need to have mechanisms to allow the arms to pivot horizontally, but still retaining a similar amount of functionality as would be provided by implementing horizontal pivoting of the arms.

Floor-Based Embodiments

In one embodiment, the machine described in FIG. 1 includes ones wherein components such as motors are placed lower, such as near to or on the ground. Floor-based machines described herein have various benefits and/or improvements. For example, a floor-based configuration

may be designed to not require arms (202, 204) that have degrees of freedom. The degrees of freedom of arms may be expensive, for example because the arms not only need to pass loads through them, but also be lockable and adjustable. Furthermore, the use of arms may necessitate wall mounting of an exercise machine, which may introduce further installation cost and complexity. Thus, the removal or non-use of such degrees of freedom may allow for less expensive and complex exercise machines while still providing a useful exercise regime.

In one embodiment, floor-based machines are used in conjunction with auxiliary pulleys and/or other cable ends, so that users of the exercise machines and/or weight trainers are configured to pull down on a cable coupled to a cable, for example, retracting cables downward toward the floor. This may mimic the action of weights pulling downwards. In one embodiment, the user stands on the exercise machine. In one embodiment, the user sits on the exercise machine.

One example of a floor-based configuration of a weight machine is a platform or step. A platform configuration of a digital exercise device/trainer has various benefits and/or improvements. For example, it may be portable since it need not be mounted. This allows the exercise machine to be stored away efficiently and/or safely.

Exercise Device Powertrain/Drivetrain

As shown in FIG. 1B, the drivetrain comprises parts (B103), (B104), (B200), (B201), (B203), (B205), (B300)/(B301), (B303)/(B305), (B401)/(B403), and (B501)/(B503). The drivetrain also comprises the motor (B100). The drivetrain does work on the user in order to extract energy from them, wherein the user may be seen as an energy reservoir. The physical relationship that

$$\text{Power} = \text{Force} \times \text{Velocity}$$

describes that if the actuator velocity/speed and/or cable velocity/speed increases, power of the motor (B100) and drivetrain increases as well since force, or the simulated weight, is held constant. Similarly, as torque and rotational speed are related to force and velocity,

$$\text{Torque} = \frac{1}{2\pi} \frac{\text{Power}}{\text{Rotational Speed}}$$

wherein rotational speed is based upon supply voltage of the motor (B100) and torque generated is related to phase current of the motor (B100).

Two motor constants may be used to describe characteristics of the one or more drivetrain motors (B100). The torque constant or K_t as referred to herein relates the phase current of a motor and generated torque such that

$$K_t = \frac{\text{Torque}}{\text{Phase Current}}$$

and the back EMF constant or K_e as referred to herein relates the back EMF generated by the motors (B100) and their rotational speed such that

$$K_e = \frac{\text{Back EMF Generated}}{\text{Rotational Speed}}$$

For a given motor (B100), gearing allows an exchange of rotational speed for torque, wherein the gearing may come from a gearbox, spool diameter, and/or belt drive reduction, for example. Gearboxes and spools may have user experience and inertia impacts but result in a more efficient system, and geared motors may be smaller for the same torque when compared to a direct drive motor.

The drivetrain operations in at least three modes: a motoring mode wherein electrical power sent from an electrical power supply unit (PSU) to the motor so that the motor does mechanical work on the user; a generator mode wherein the user does mechanical work on the motor and the user's power is dissipated and/or reused within the drivetrain and/or motor; and a shared power mode when the user input power is less than the motor losses, as summarized in Table 1:

Drivetrain Components used in each Mode					
User Direction	Mode	Motor	Controller	Shunt	Power Supply Unit
Eccentric	Motoring	Yes	Yes	No	Yes
Concentric	Generator	Yes	Yes	Yes	No
	Shared Power	Yes	Yes	No	Yes

FIG. 3 is a diagram illustrating an example of a low speed and high weight mode for the differential. The graph shown in FIG. 3 has along the x-axis the actuator speed in inches per second (IPS) and along the y-axis the system power in watts. For a low speed and/or high weight user exertion there is a transition point (302) between the transition from generator mode and shared power mode during a concentric user direction. The location of the actuator speed transition point (302) depends on the target weight, due in part to motor electrical resistance losses:

$$P_{shunt} = P_{mech\_from\_user} - (P_{losses\_motor} + P_{losses\_controller})$$

which as shown in FIG. 3 is around 80 inches per second (302). In FIG. 3 as shown, the shared power mode (304) is shown between 0 and around 80 inches per second with PSU power decreasing from 800 watts to 0 watts, and after the transition point (302) is replaced by the generator mode (306) shown between around 80 inches per second to 200 inches per second with user power increasing from 0 watts to around 1300 watts. As an example of showing how this graph in FIG. 3 changes for a target weight, the PSU power, transition point, and shunt power is shown for a 75 lb target weight with solid line (308), and the PSU power, transition point, and shunt power is shown for a 35 lb target weight with dotted line (310), showing that the transition point will be at a lower actuator speed for a 35 lb target weight, around 60 inches per second.

FIG. 4 is a diagram illustrating a power sharing mode example. The graph shown in FIG. 4 has along the x-axis a timeline in seconds from 0 to 300 seconds of an exercise movement, and along the primary y-axis for the power in watts, for the PSU supplied power (402) and the user

supplied power (404), and along the secondary y-axis for the cable speed (406) in inches per second.

As shown in FIG. 4, a concentric phase (410) of the user exercise movement happens between around 60 seconds and around 230 seconds. The concentric phase (410) starts with a shared power mode (412) between around 60 seconds and 160 seconds where the PSU supplied power (402) decreases from around 500 watts to 0 watts, the user supplied power changes from 0 watts to around 500 watts, and the cable speed increases from 0 inches per second to around 40 inches per second. The concentric phase (410) then traverses a generator mode (414) between 160 seconds and 200 seconds where the PSU supplied power (402) remains at 0 watts, the user supplied power peaks from -500 watts to -600 watts and returns to -500 watts, and the cable speed peaks from 40 inches per second to 60 inches per second and returns to 40 inches per second. The concentric phase (410) returns to a shared power mode (415) between 200 seconds and around 230 seconds where the PSU supplied power (402) increases from 0 watts to around 500 watts, the user supplied power changes from -500 watts to 0 watts, and the cable speed decreases from 40 inches per second to 0 inches per second.

As shown in FIG. 4, the eccentric phase (416) of the user exercise movement happens between around 230 seconds and 300 seconds, comprising the motoring mode (416) where the PSU supplied power (402) increases from 500 watts to around 600 watts, the user supplied power changes between 0 watts to around 40 watts, and the cable speed changes from 0 inches per second to around-5 inches per second.

Note that in FIG. 4 the direction of power flow is referred to herein as positive from the PSU and negative from the user. That is, curve (404) is negative for the concentric phase (410) as the user is injecting power into the motor, and during the eccentric phase curve (416) is positive as the PSU drives the motor. Note that in FIG. 4 the direction of cable speed is referred to herein as positive in an outward direction, that is the cable is spooling outward from the motor, and cable speed is negative in an inward direction, that is the cable is spooling inward towards the motor.

FIG. 5A is a diagram illustrating a concentric phase drivetrain energy flow. In one embodiment, the controller/processor (506) of FIG. 5A is a block representing the controller (104) and/or processor (102) of FIG. 1A, housed in electronics bay (B720) of FIG. 1B. In one embodiment, the motor (508) of FIG. 5A is a block representing one or more motors (106) of FIG. 1A and/or motors (B100) of FIG. 1B. In one embodiment, the resistive shunt (512) of FIG. 5A is housed in electronics bay (B720) of FIG. 1B. The shared power mode of FIG. 5A is given as an example (412) in FIG. 4. The generator mode of FIG. 5A is given as an example (414) in FIG. 4.

In the concentric phase of a user exercise movement, the user is pulling on the actuator (110) in FIG. 1A, for example to start a bicep curl exercise movement when the user is pulling an actuator (110) upwards contracting the biceps, where the user input power, proportional to the user pull speed, is shared with the PSU input power. During the concentric phase the actuator (110) and cable (108) of FIG. 1A is being pulled out of the exercise device in what is referred to as an outward direction for actuator velocity and/or cable velocity.

At the start of a concentric phase in a user exercise movement, in shared power mode the electrical receptacle (502) provides energy to a PSU (504) with resistive/switching heat losses and outputs energy to the controller/proces-

sor (506). The controller/processor (506) provides energy to one or more motors (508) along with resistive/switching heat losses. The user (510) also provides energy to the one or more motors (508), and the motor(s) (508) have their own friction/windage losses due to the iron/copper in the motor. The remaining energy is shunted to resistive shunt (512) where it is dissipated as resistive heat.

Next in the concentric phase in a user exercise movement, in the event the user input power is high enough that the PSU provides zero power, generator mode replaces the shared power mode. The dotted line of FIG. 5A is no longer part of the energy flow when the PSU (504) provides zero power. The user (510) provides all energy to one or more motors (508), which have their friction/windage losses and provide energy to controller/processor (506). The controller/processor (506) have their resistive/switching heat and net energy to the shunt (512) with its resistive heat dissipating all remaining energy.

As shown in FIG. 5A, concentric phase user exercise movements require the user (510) to provide power to the motor(s) (508). The exercise device is speed/velocity limited in the concentric phase by back EMF generated by the motor(s) (508) as compared with electronic component voltage ratings in the drivetrain, associated with the K_e of the motors (508). The exercise device is power/torque limited in the concentric phase by phase current rating/heat rejection capacity on the inverter circuit(s) in the controller (506) and other drivetrain electronic components, and the shunt pulse power rating of the shunt (512). The exercise device is thermally limited by the motor(s) (508) cooling capacity which is related to the K_t of the motors (508) in that a smaller K_t results in higher phase current for a given torque and higher loss from I^2R resistive losses. The exercise device is also thermally limited by the shunt (512) average power rating and cooling capability. The exercise device is also thermally limited by the weight requested by the user, which is proportional to the amount of torque requested from the motor, which increases the phase current and thus higher loss from I^2R resistive losses.

Thus, the exercise device is constrained by the amount of power and speed the user (510) is inputting into the system shown in FIG. 5A. Power being generated by the user (510) may get absorbed by the motors (508) and controller/processor (506) before reaching the shunt (512) and/or being provided by the PSU (504). The distribution of power being shared is dependent on the motor torque and cable speed given the constant force system described above.

FIG. 5B is a diagram illustrating an eccentric phase drivetrain energy flow. In one embodiment, the controller/processor (506) of FIG. 5B is a block representing the controller (104) and/or processor (102) of FIG. 1A, housed in electronics bay (B720) of FIG. 1B. In one embodiment, the motor (508) of FIG. 5B is a block representing one or more motors (106) of FIG. 1A and/or motors (B100) of FIG. 1B. The motoring mode of FIG. 5B is given as an example (416) in FIG. 4.

In the eccentric phase of a user exercise movement, the electrical receptacle (502) is performing work on the user (510) holding onto the actuator (110) in FIG. 1A, for example to end a bicep curl exercise movement when the user is allowing the actuator (110) to return downwards, slightly relaxing the biceps in comparison to the concentric phase. During the eccentric phase the actuator (110) and cable (108) of FIG. 1A are being pulled back in to the exercise device in what is referred to as an inward direction for actuator velocity and/or cable velocity.

In the eccentric phase in a user exercise movement, the electrical receptacle (502) provides energy to a PSU (504) with resistive/switching heat losses and outputs energy to the controller/processor (506). The controller/processor (506) provides energy to one or more motors (508) along with resistive/switching heat losses. The one or more motors (508) perform work on the user (510), and the motor(s) (508) have their own friction/windage losses due to the iron/copper in the motor.

As shown in FIG. 5B, eccentric phase user exercise movements require power to be provided to the motors (508) from the power supply (504). The exercise device is power limited in the eccentric phase by the electrical receptacle rating, for example a typical residential outlet may provide 120V AC at 15 Amps with a UL derating of 20% providing 1,440 of watts of continuous power. The exercise device is also power limited in the eccentric phase by the PSU (504) ratings as the DC PSU (504) is rated for average power, and design/regulatory requirements for the controller/processor (506), motors (508) are higher in complexity for voltage over 60V DC, for example a 120 VAC to 48 VDC power supply may be used with its ratings and limits. Transient peak power requirements, average power requirements, and efficiency are the power supply (504) ratings and limits that affect power limiting in the eccentric phase.

The exercise device is speed/velocity limited in the eccentric phase by the K_e of the motors (508) and the PSU (504) supply voltage, for example with 15% margin a maximum actuator/cable speed is

$$\text{Maximum Speed} = 115\% \times V_{DC} \times K_e$$

The exercise device is thermally limited by the motor(s) (508) cooling capacity which is related to the K_r of the motors (508) in that a smaller K_r results in higher phase current for a given torque and higher loss from I^2R resistive losses. The exercise device is also thermally limited by the weight requested by the user, which is proportional to the amount of torque requested from the motor, which increases the phase current and thus higher loss from I^2R resistive losses.

FIG. 6 is a diagram illustrating an example concentric boost mode for a digital exercise machine. In one embodiment, the system of FIGS. 1A and 1B is used to process the concentric boost mode of FIG. 6.

The graph shown in FIG. 6 has along the x-axis a timeline of an exercise movement and a partial subsequent exercise movement, along a primary y-axis motor tension (602), along a secondary y-axis cable speed/velocity (604), and along a tertiary y-axis cable position (606). As depicted in FIG. 6, a user exercise movement goes through at least four stages, a concentric phase (612) when the cable is being drawn outwards from the exercise machine as the user for example begins pulling a bicep curl upwards, a top hold phase (614) when the user for example holds the bicep curl at its apex, an eccentric phase (616) when the cable is being drawn inwards to the exercise machine as the user for example begins dropping the bicep curl downwards, and a bottom hold phase (618) when the user for example relaxes the bicep curl at its nadir.

As shown in FIG. 6, the concentric phase (612) may be identified by the system when the actuator velocity and/or cable velocity (606) is in an "outward direction", which as referred to herein is when the actuator velocity and/or cable velocity (606) is positive. A hysteresis curve may be estab-

lished where the concentric phase (612) may be identified for an increased amount of torque requestable only after an actuator and/or cable velocity engagement threshold is reached, for example three inches per second. In one embodiment, the velocity engagement threshold is based on a saturation point, wherein the saturation point is based at least in part on a user requested weight, current drawn from a power supply coupled to the motor, a lower torque bound for requestable torque from the motor, a higher torque bound for requestable torque from the motor, and losses in the motor.

As shown in FIG. 6, the eccentric phase (616) may be identified by the system when the actuator velocity and/or cable velocity (606) is in an "inward direction", which as referred to herein is when the actuator velocity and/or cable velocity (606) is negative.

For the example system shown in FIG. 6, the power supply alone can provide at most 150 lbs of motor tension (622). Thus, a user doing a bicep curl exercise movement may specify to the exercise machine at most a "150 lb" set of bicep curls for a symmetric exercise movement, meaning at most "150 lb" of weight for the bicep curls in the concentric and eccentric phases.

A concentric boost mode is disclosed, wherein the user may specify to the exercise machine a "boost mode" referred to herein as an increased amount of torque requestable from the motor. Thus, a user doing a bicep curl exercise movement may specify to the exercise machine a "150 lb+Boost" set of bicep curls for an asymmetric exercise movement, meaning that during at least a portion of the user exercise movement in which the actuator velocity is in the outward direction and/or concentric phase, the user experiences a boosted increased weight, shown in FIG. 6 to be up to 200-225 lbs or around a 35% increase based on the drivetrain limits described above and in FIGS. 5A and 5B and the user's targets. The maximal boost weight is derived from a power balance where the boost force must be equal or less than

$$F_{max} = \left(\frac{P_{supply} - P_{losses}}{V_{user}} \right)$$

After the concentric phase the eccentric bicep curl would return to 150 lb of weight experienced by the user. In summary, during the eccentric/inward phase, all power comes from the electrical receptacle, and during the concentric/outward phase, both the user and the electrical outlet are supplying power to the exercise device.

An improvement of concentric boost mode is that physiological studies have shown that increased strength and power output may be unlocked primarily in the concentric phase for a given user exercise movement such as bicep curl, bench press, and lat pulldown. Another improvement of concentric boost mode is that physiological studies have shown that increased concentric phase exercise and/or asymmetric exercise movements have increased hypertrophy and/or muscle growth potential. Another improvement of concentric boost mode is that physiological studies have shown that a user experiences reduced muscle damage and/or soreness when strain is shifted to concentric.

Exercise Device Inertia. Different digital exercise devices with different drivetrain designs have different resistance profiles, in part because the weight dynamics are different with for example a different number of motors and gearboxes. Using the processor (102) and/or controller (104) of

FIG. 1A, allowing a first digital exercise device to emulate the resistance profile of a second digital exercise device is disclosed.

FIGS. 7A, 7B(1), and 7B(2) are diagrams illustrating an example of two different exercise devices with different drivetrain designs. FIG. 7A is a free body diagram of a one-motor exercise machine that has a single motor that drives two actuators via a differential gearbox, similar to that shown in FIGS. 1A, 1B, and 2. FIG. 7B(1) is a free body diagram of a two-motor exercise machine that has each of two motors drive one actuator without a differential gearbox, and wherein only one of the motors is shown in FIG. 7B(1).

In one embodiment, the two-motor exercise device comprises a singular motor which is spinning with a spool on it, and a user pulls directly against the motor via a cable and actuator, with frictional losses that happen as the cable goes across sheaves. With a smaller radius of the motor, a smaller mass that a user is spinning, so a smaller moment of inertia in comparison to the one-motor exercise device.

In one embodiment, the one-motor exercise device has a motor which is a bigger diameter motor and a heavier outer ring of magnet, with a larger moment of inertia. Note that moment of inertia tracks against a given mass as well as the geometry of a spinning object, so the motor itself has a higher moment of inertia. The one-motor exercise device also has a differential as a flywheel of steel that is spinning around in circles concentrically, adding another larger moment of inertia in comparison to the two-motor exercise device.

As a same or similar user is pulling on a cable for the two-motor exercise device versus the one-motor exercise device, the user pulling the one-motor exercise device has to accelerate both the differential and the bigger diameter motor up in comparison to the user pulling the two-motor exercise device with its smaller diameter motor. As Newton's Second Law of Motion describes that force equals mass times acceleration, the two devices have different mass or inertia for the device user's actuator. From the perspective of the motor, that mass/inertia may be described from the moment of inertia of each device's drivetrain. For example, an equivalent mass/inertia for a one-motor device may be between 23-25 lbs, whereas in one example, an equivalent mass/inertia for a two-motor device may be around 3 lbs.

It would be useful for a user of the two-motor device to provide a user experience of an equivalent 23-25 lb inertia exercise device for a larger weight requested during a user exercise movement, say for a request over 30 lb. It would be useful for a user of the one-motor device to provide a user experience of an equivalent 3 lb inertia exercise device for a smaller weight requested during a user exercise movement, say for a request under 30 lb.

One-Motor Free Body Diagram. Similar to that shown in FIGS. 1A, 1B, and 2, the one-motor exercise machine includes a motor (706), belt (710), differential (704), spools (702), and actuator cables (708). For the free body diagram of FIG. 7A, the following definitions are used:

-continued

Variable	Definition	Units
α_m	Motor (706) Angular Acceleration	$\frac{\text{rad}}{\text{s}^2}$
α_{Ls}	Left Spool (702) Angular Acceleration	$\frac{\text{rad}}{\text{s}^2}$
α_{Rs}	Right Spool (702) Angular Acceleration	$\frac{\text{rad}}{\text{s}^2}$
α_d	Differential Ring Gear (704) Angular Acceleration	$\frac{\text{rad}}{\text{s}^2}$
α_L	Left Cable (708) Linear Acceleration	$\frac{\text{m}}{\text{s}^2}$
α_R	Right Cable (708) Linear Acceleration	$\frac{\text{m}}{\text{s}^2}$
g	Acceleration of gravity	$\frac{\text{m}}{\text{s}^2}$
I_m	Motor (706) Moment of Inertia	$\text{kg} * \text{m}^2$
I_d	Differential (704) Moment of Inertia	$\text{kg} * \text{m}^2$
m_1	Mass of hanging object	kg
m_u	Equivalent point-mass of part of user's body	kg
F_u	Force applied by user	N

The following assumptions are made for a simplifying physics analysis:

A load applied to both arms is the same;

No friction analyzed;

100% efficient differential;

100% efficient belt drive; and

Frictionless bearings.

15 The motor rotating body equations to sum torques and solve for T_2 :

$$\begin{aligned} \Sigma \tau &= I_m \alpha_m \\ T_2 R_m - \tau_m &= I_m \alpha_m \\ T_2 &= \frac{I_m \alpha_m + \tau_m}{R_m} = \frac{I_m \alpha_m}{R_m} + \frac{\tau_m}{R_m} \end{aligned}$$

20 When both cables are pulled, the differential is locked so that spool and differential angular velocity/acceleration are the same. The differential rotating body equations to sum torques and solve for T_2 :

$$\begin{aligned} \Sigma \tau &= I_d \alpha_d + I_s \alpha_{LS} + I_s \alpha_{RS} \\ \text{where } \alpha_{LS} &= \frac{a_L}{R_s} \text{ and } \alpha_{RS} = \frac{a_R}{R_s} \\ \Sigma \tau &= I_d \alpha_d + \frac{I_s a_L}{R_s} + \frac{I_s a_R}{R_s} \end{aligned}$$

25 The differential applies the same torque to both spools.

$$2T_1 R_s - T_2 R_d = \Sigma \tau$$

$$2T_1 R_s = T_2 R_d = I_d \alpha_d + \frac{I_s a_L}{R_s} + \frac{I_s a_R}{R_s}$$

$$T_2 R_d = 2T_1 R_s - I_d \alpha_d - \frac{I_s a_L}{R_s} - \frac{I_s a_R}{R_s}$$

Variable	Definition	Units
R_s	Radius of the Spool (702)	m
R_d	Radius of the Differential Ring Gear (704)	m
R_m	Radius of the Motor (706)	m
τ_m	Torque applied by the motor (706)	Nm
T_1	Tension in either cable (708)	N
T_2	Tension in the belt (710)	N

-continued

$$T_2 = \frac{2T_1R_s}{R_d} - \frac{I_d\alpha_d}{R_d} - \frac{I_s(a_L + a_R)}{R_sR_d}$$

Equating the left and right cable acceleration to the differential spool angular acceleration:

$$\alpha_{LS} + \alpha_{RS} = \alpha_d$$

$$\frac{a_L + a_R}{R_s} = \alpha_d$$

And equating the differential and motor angular accelerations using the belt as the connecting element:

$$\alpha_dR_d = \alpha_mR_m$$

$$\alpha_d = \frac{R_m\alpha_m}{R_d}$$

Then equating the cable acceleration to the motor angular acceleration:

$$\frac{R_m\alpha_m}{R_d} = \alpha_d = \frac{a_L + a_R}{R_s}$$

$$R_sR_m\alpha_m = R_d(a_L + a_R)$$

$$\alpha_m = \frac{R_d(a_L + a_R)}{R_sR_m}$$

Equating the differential belt tension and motor belt tension:

$$T_2 = T_2$$

$$\frac{2T_1R_s}{R_d} - \frac{I_d\alpha_d}{R_d} - \frac{I_s(a_L + a_R)}{R_sR_d} = \frac{I_m\alpha_m}{R_m} + \frac{\tau_m}{R_m}$$

Solving for the cable tension T_1 :

$$\frac{2T_1R_s}{R_d} = \frac{\tau_m}{R_m} + \frac{I_m\alpha_m}{R_m} + \frac{I_d\alpha_d}{R_d} + \frac{I_s(a_L + a_R)}{R_sR_d}$$

$$T_1 = \frac{\tau_mR_d}{2R_sR_m} + \frac{I_m\alpha_mR_d}{2R_sR_m} + \frac{I_d\alpha_d}{2R_s} + \frac{I_s(a_L + a_R)}{2R_s^2}$$

Substituting in the α_m derived above:

$$\alpha_m = \frac{R_d(a_L + a_R)}{R_sR_m}$$

$$T_1 = \frac{\tau_mR_d}{2R_sR_m} + \frac{I_mR_d^2(a_L + a_R)}{2R_s^2R_m} + \frac{I_d\alpha_d}{2R_s} + \frac{I_s(a_L + a_R)}{2R_s^2}$$

Substituting in the α_d derived above:

$$\alpha_d = \frac{a_L + a_R}{R_s}$$

-continued

$$T_1 = \frac{\tau_mR_d}{2R_sR_m} + \frac{I_mR_d^2(a_L + a_R)}{2R_s^2R_m} + \frac{I_d(a_L + a_R)}{2R_s^2} + \frac{I_s(a_L + a_R)}{2R_s^2}$$

Solving in terms of motor acceleration:

$$\alpha_m = \frac{R_d(a_L + a_R)}{R_sR_m}$$

$$(a_L + a_R) = \frac{\alpha_mR_sR_m}{R_d}$$

Substituting the left and right cable accelerations for motor angular acceleration to only use motor parameters:

$$T_1 = \frac{\tau_mR_d}{2R_sR_m} + \frac{I_m\alpha_mR_d}{2R_sR_m} + \frac{I_d\alpha_mR_m}{2R_sR_d} + \frac{I_s\alpha_mR_m}{2R_sR_d} \quad (\text{Equation EQ2})$$

Two-Motor Free Body Diagram.

The two-motor exercise machine includes a motor (752) and actuator cables (754). For the free body diagram of FIG. 7B(1), the following definitions are used:

Variable	Definition	Units
R_m	Radius of the motor (752)	m
τ_m	Torque applied by the motor (752)	N * m
T_1	Tension in the cable (754)	N
m_1	Mass of hanging object	kg
I_m	Motor (752) Moment of Inertia	kg * m ²
α_m	Motor (752) Angular Acceleration	$\frac{\text{rad}}{\text{s}^2}$
a	Cable (754) acceleration	$\frac{\text{m}}{\text{s}^2}$
g	Acceleration of gravity	$\frac{\text{m}}{\text{s}^2}$
m_u	Equivalent point-mass of part of user's body	kg
F_u	Force applied by user	N

The following assumptions are made for a simplifying physics analysis:

No windage;

Dynamic friction only, lumping effects of the sheaves/cable bending together; and

Ignore the moment of inertia of other sheaves in the system.

The motor rotating body equations to solve for T_1 when the motor torque directly opposes the user force applied at the cable (754):

$$T_1R_m - \tau_m = I_m\alpha_m$$

$$T_1 = \frac{\tau_m}{R_m} + \frac{I_m\alpha_m}{R_m}$$

Equating the cable acceleration to the differential angular acceleration:

$$a = R_m \alpha_m$$

$$\alpha_m = \frac{a}{R_m}$$

And substituting motor angular acceleration into the tension equation:

$$T_1 = \frac{\tau_m}{R_m} + \frac{I_m \alpha_m}{R_m^2}$$

Resistance Profile Emulation.

As shown in FIG. 7A and FIG. 7B(1), the drivetrain of a two-motor system, termed herein an “E” system, is simpler than the drivetrain of a one-motor system, termed herein a “C” system. An “E” system may mimic the user experience and/or an experienced inertia when a user exceeds a certain requested weight, say 30 lbs. That is, a user may enjoy the lower weight dynamics of a simpler “E” system for requested weights less than e.g. 30 lb but also enjoy the challenge of a “C” system at requested weights more than e.g. 30 lb.

To provide the physical analysis for this emulation, the equation of motion derived above for the “C” one-motor system and the equation of motion for the “E” two-motor system are solved for a phantom moment of inertia to be added to the “E” system:

Starting with the “C” system cable tension, using the “c” subscript for the “C” system:

$$T_1 = \frac{\tau_{mc} R_d}{2R_s R_m} + \frac{I_{mc} R_d^2 (a_L + a_R)}{2R_s^2 R_m^2} + \frac{I_d (a_L + a_R)}{2R_s^2} + \frac{I_s (a_L + a_R)}{2R_s^2}$$

Comparing the “E” system with two motors, each motor is in control of a single side, so one side may be dropped from the “C” system acceleration:

$$T_1 = \frac{\tau_{mc} R_d}{2R_s R_m} + \frac{I_{mc} R_s^2 a}{2R_s^2 R_m^2} + \frac{I_d a}{2R_s^2} + \frac{I_s a}{2R_s^2}$$

The “E” system cable tension, using the “e” subscript for the “E” system:

$$T_1 = \frac{\tau_{me}}{R_{me}} + \frac{I_{me} a}{R_{me}^2}$$

To make an “E” system feel like a “C” system comprises having the same force response to applied accelerations. This may be accomplished by adding a new term to the “E” system’s tension:

$$T_1 = \frac{\tau_{me}}{R_{me}} + \frac{I_{me} a}{R_{me}^2} + \frac{X a}{R_{me}^2}$$

Setting the cable tensions so they equal and solving for the extra moment of inertia to reach equilibrium:

$$5 \quad \frac{\tau_{me}}{R_{me}} + \frac{I_{me} a}{R_{me}^2} + \frac{X a}{R_{me}^2} = \frac{\tau_{mc} R_d}{2R_s R_m} + \frac{I_{mc} R_d^2 a}{2R_s^2 R_m^2} + \frac{I_d a}{2R_s^2} + \frac{I_s a}{2R_s^2}$$

Equalizing the motor torques as these are the weight dial portions:

$$15 \quad \frac{I_{me} a_L}{R_{me}^2} + \frac{X a_L}{R_{me}^2} = \frac{I_{mc} R_d^2 a_L}{2R_s^2 R_m^2} + \frac{I_d a_L}{2R_s^2} + \frac{I_s a_L}{2R_s^2}$$

Solving for “X” provides the additional moment of inertia to be multiplied by the angular acceleration to feel the same as the “C” system:

$$20 \quad X = \left(\frac{I_{mc} R_d^2}{2R_s^2 R_m^2} + \frac{I_d}{2R_s^2} + \frac{I_s}{2R_s^2} \right) R_{me}^2 - I_{me}$$

25 Thus, when an “C” system emulation mode is enabled, for example for a requested weight for a user exercise movement exceeds a threshold amount, then the torque controller (104) of FIG. 1A adjust torque that is requested of the motor (106) to generate an experienced inertia by adding X multiplied by the angular acceleration to the mechanical inertia of the actuator related to the moment of inertia I_{me} of the “E” system.

Slack Control.

30 The above Equation (EQ1) describes, for a user pulling on a cable, how motor torque applied is related to acceleration of the motor, spools, cables, and differential. Note that in Equation (EQ1) that the terms of R_d , R_s , R_m , I_m , I_d , and I_s are constants in the sense that they are fixed parameters once the drivetrain is designed and implemented for a given exercise device.

35 For example, if the actuator is not moving, the actuator and cable acceleration components of Equation (EQ1), a_L and a_R are zero, simplifying the relationship between cable tension and motor torque as a function of radius/sizes of the motor, differential, and spool:

$$45 \quad T_1 = \frac{\tau_m R_d}{2R_s R_m}$$

50 when a_L and a_R are zero, wherein the relationship may be thought of as T_1 equal to a constant multiplied by τ_m .

Issues may arise when the cable comes loose inside an exercise machine due to gravity acting in a different direction than the spooling and tension force. This gravity direction 55 may depend on the mounting of the motor, whether mounted vertically, horizontally, or at an angle between vertically and horizontally.

For example, suppose that when the user is performing an exercise, the user accelerates when in the eccentric direction where the cable is retracting. In this case, the user is moving 60 inwards faster than the motor can take up the slack in the cable, generating what is referred to herein as a slack condition, or slack, in the direction towards the machine.

Similarly, when the user is pulling outwards on the cable 65 and suddenly stops, this may result in an inertial issue in which a slack condition is produced. The inertia of the motor causes the motor to continue to travel before torque regen-

eration may stop the motor and allow it to reverse. During that time frame, a slack condition is created, where there is no tension on the cable, as the motor's inertia is greater than the torque that the motor is producing. Thus, the above two slack conditions are dependent on the maximum linear speed that may be imparted on the motor, as well as the inertia of the motor. Slack conditions may cause a cable to no longer be inline with the spool/motor, in which case the cable may then potentially become bound, jammed, and/or tangled. For example, when the cable slacks and the motor takes up the cable in a random fashion, this may cause a large knot to form around the motor's axle.

The above Equation (EQ1) also describes, when no user force is applied in the system when T_1 is zero, how acceleration of the system is related to a given motor torque. When slack occurs, there is no user force being applied in the system as the cable is loose, so Equation (EQ1) better identifies when slack conditions occur in order to change behaviors/system dynamics, allowing the improvement to react to slack conditions faster:

$$\frac{\tau_m R_d}{2R_s R_m} + \frac{I_m R_d^2 (a_L + a_R)}{2R_s^2 R_m^2} + \frac{I_d (a_L + a_R)}{2R_s^2} + \frac{I_s (a_L + a_R)}{2R_s^2} = 0 \text{ during a slack condition.}$$

In one embodiment, T_1 is not directly measured in an exercise device for an improvement in power reduction, materials reduction, and cost reduction, but motor position measurement is available. In one embodiment, the cable tension is derived from the estimated motor torque, the system geometry and the moment of inertia. Due to the mechanical linkage between motor position and cables, the motor position correlates a_L and a_R to determine the linear acceleration of either cable. The motor position measurement may thus be used in conjunction with the radius of drivetrain components and the moment of inertia of drivetrain components to determine an estimate of motor torque provided. Note again that for the motor, τ_m is equal to K_t multiplied by I , wherein K_t is the torque constant of the motor and I is the motor's phase current, which can be driven by the exercise device, for example by supplying 32 amps worth of phase current to provide a requested weight of 50 lbs for a given user exercise movement. Continuing with slack control, if a user stops pulling, then τ_m is equal to a constant multiplied by $(a_L + a_R)$. Using the motor position measurement to determine a_L and a_R the estimated motor torque may be determined using this equation to predict how the system decelerates during the potential slack condition, or put another more direct way in terms of motor phase current in a potential slack condition, for example:

$$I = \frac{-2R_s R_m}{R_d K_t} \left(\frac{I_m R_d^2}{2R_s^2 R_m^2} + \frac{I_d}{2R_s^2} + \frac{I_s}{2R_s^2} \right) (a_L + a_R)$$

Outward Slack Control.

During an example outward slack condition, the user is pulling outwards on the cable and suddenly stops, for example a user is doing a bicep curl exercise movement in the concentric phase and comes to a complete halt. To reduce the inertial issue where the inertia of the motor causes the motor to continue to travel producing slack, the motor position is used in part to identify the slack condition. Once an outward slack condition is identified, the exercise device

increases the requested torque to bring the rotating mass to a near stop to reduce cable slack. In one embodiment, the outward slack condition monitoring vigilance is enhanced by detecting using motor position when a user is beginning and ending a concentric phase of a user exercise movement and allocating more resources to outward slack condition monitoring when a concentric phase is detected.

Inward Slack Control.

During an example inward slack condition, the user accelerates the actuator in the eccentric phase wherein the cable is retracting, for example a user is doing a bicep curl exercise movement in the eccentric phase and either drops their actuator completely down suddenly, or lets go of the actuator. To reduce the inertial issue where the user is moving inwards faster than the motor can take up the slack in the cable, the relationship described in Equation (EQ1) is used to identify the slack condition wherein T_1 is zero. That is, the processor observes a_L and a_R as large as possible given the amount of motor torque provided, meaning the user is likely not imposing any tension.

Once a slack condition is identified, the exercise device begins matching the cable acceleration by changing the motor phase current to affect the motor torque per the relationship described in Equation (EQ1), in part to consume any cable slack to a point where T_1 is larger than zero. In one embodiment, the inward slack condition monitoring vigilance is enhanced by detecting using motor position when a user is beginning and ending an eccentric phase of a user exercise movement and allocating more resources to inward slack condition monitoring when an eccentric phase is detected.

FIG. 8 is a diagram illustrating the traditional four modes of a motor. In one embodiment, the motor (106) of FIG. 1A or the motor (B100) of FIG. 1B is similar to the motor shown in FIG. 8.

As shown in FIG. 8, a quadrant of forward motion and reverse motion crossed with motoring and braking/generation is due to the electromagnetic field of the motor. Adopting the convention that forward motion is outward motion and reverse motion is inward motion, for the exercise device described herein, the motor (106) of FIG. 1A or the motor (B100) of FIG. 1B in the concentric phase engages the user in quadrant 1 forward motoring (802) during the shared power mode, and then possibly quadrant 2 forward generation/braking (804) during the generator mode. In the eccentric phase, the motor engages the user in quadrant 3 reverse motoring (806) during the motoring mode. Thus outwards slack conditions are generally when the motor (106)/(B100) is in quadrant 2 forward generation/braking/resisting (804), and inward slack conditions are generally when the motor (106)/(B100) is in quadrant 3 reverse motoring (806). Thus, torque for both outward slack conditions and inward slack conditions are applied in the same direction, wherein when motor phase current/is increased it increase braking in an outward slack condition, and wherein when motor phase current/is increased, it increases motoring/acceleration in an inward slack condition.

Experienced Inertia different from Mechanical Inertia.

Starting with quadrant 1 forward motoring (802) during the shared power mode of a concentric phase within a user exercise movement, without compensation the user pulling the actuator experiences an inertia which is referred to herein as the mechanical inertia of the actuator. For a user of a "C" one-motor exercise device, the user experience may be improved if they experience a different experienced inertia, referred to herein as the effective inertia experienced by a user pulling the actuator. For example the experienced

inertia of a "C" one-motor exercise device may be, for lower requested weights for a user exercise movement, the mechanical inertia of an "E" two-motor exercise device. For example, for lower requested weights, if a "C" machine has larger drivetrain inertia, it is hard to do lower weight exercise movements like shoulder rotator cuff type exercises, especially for weaker individuals. Allowing weaker or injured individual to do training and/or exercise to in part strengthen or heal injuries is an improvement. Dynamically changing the experienced inertia apart from the mechanical inertia of the actuator is disclosed.

Returning to Equation (EQ1), if T_1 is small and less than a threshold, say 3 lb which is less than a threshold of 30 lb, the exercise device asserts phase current to the motor (106)/(B100) to adapt τ_m based on what the cable acceleration values a_L and a_R are, effectively executing a control loop on τ_m . This may be simplified further given that cable acceleration values a_L and a_R are derived from a motor position encoder, to instead use Equation (EQ2) relating T_1 , τ_m , and α_m , the angular acceleration of the motor which may be estimated as a second derivative of angular position of the motor with respects to time. Asserting phase current to the motor (106)/(B100) and/or adjusting motor torque to execute a control loop on τ_m based on what the motor acceleration α_m for a given requested T_1 is disclosed. This control loop may be asserted in all three quadrants of FIG. 8, including the shared power mode, generator mode, and/or motoring mode in concentric phase and eccentric phase of a user exercise movement.

Note that a converse case may also use the improvement of experienced inertia. For example, for a user of an "E" two-motor exercise device, the user experience may be improved if they experience a different experienced inertia, such as that of the mechanical inertia of a "C" one-motor exercise device for higher requested weights for a user exercise movement. For example, for higher requested weights, if an "E" machine has smaller inertia, higher weight exercise movements like dead lift type exercises seem different from the same exercises performed with an actual physical barbell. Allowing users to do training and/or exercise to better emulate actual physical exercise is an improvement. Dynamically changing the experienced inertia apart from the mechanical inertia of the actuator is disclosed.

Motor Control Loop for Inwards Slack Control.

FIG. 9 is a graphical illustration of a control loop for inwards slack control. The analysis of FIG. 9 is based on Equation (EQ1) and/or Equation (EQ2). Conceptually a graph is established in the controller (104) of FIG. 1A, wherein the x-axis represents motor torque τ_m (902) and the y-axis represents motor angular acceleration α_m (904), so that several points may be empirically recorded during a calibration sequence, for example for a fixed motor torque with zero cable tension, the acceleration value is recorded at point (906). Similarly for a fixed motor torque with a cable tension of 31b, the acceleration value is recorded at point (908). After several recorded points a sloped line with y-intercept is established (910). The area (912) above the sloped line (910) is considered an inwards slack condition.

Thus during a user exercise movement, especially in the eccentric phase, in the event a recorded acceleration and torque pair (914) is below the line (910), the control loop interprets this as a user contributing power towards the system and no slack condition is detected. However, in the event a recorded acceleration and torque pair (916a) is above the line (910), the control loop interprets this as an inward slack condition and increases motor torque via motor phase current to bring the system to a point at or below the

line (916b), thus "catching up" with the hyperaccelerated cable and reducing cable slack. The line (910) may thus be thought of as a "free fall" line (910) describing maximal cable acceleration achievable with a fixed motor torque.

In one embodiment, the tension on cable T_1 is measured directly in the exercise device via for example an inline load cell. For inward slack control, in the event the tension on cable T_1 is measured to be zero at an unexpected point in the eccentric phase, the control loop interprets this as an inward slack condition and increases motor torque via motor phase current to bring the system to a point at or below the free fall line (910).

Flywheel Mode.

In one embodiment, a flywheel inertia model comprises a state space model of an emulated flywheel, in part to model fan behavior and the clutch and the ability to decay down. The state space model includes a speed of a virtual rotating object/fan, to keep track of the flywheel momentum/inertia. In one embodiment, the controller (104) of FIG. 1A comprises a speed controller on the motor wherein the speed controller detects when a user pulls the motor outwards faster, and in the event the user pulls the motor outwards faster, the target speed of the speed controller regulates and increases the cable tension/weight in order to slow down the user to match the speed of that virtual fan during the acceleration period. During this mode the amount of cable tension from Equation (EQ1) and/or (EQ2) is analyzed to estimate the amount of cable tension the user is putting into the system, and using that estimated cable tension to feed into the fan state space model to increase or decrease the virtual fan speed. A moment of inertia of the virtual fan is additionally tracked in the state space model, and a drag force of the fan in its fluid is additionally tracked in the state space model. The state space model then may estimate how this force increases the dynamics of this model to speed up/down the virtual fan and/or increase/decrease the drag of the virtual fan. So as the user initially speeds up the fan as the user applies force, dynamics of the state space model are tracked. Conversely, as soon as the user no longer applies force or is no longer moving faster than the fan blade, a clutch is modeled in the state space model, such that the user is no longer applying a load to the system. After accounting for the state space model, the amount of cable tension thus reduces back down to a nominal value for the feedback into the machine.

FIG. 10 is an illustration of an example of a flywheel mode. The graph of FIG. 10 includes an x-axis as a timeline. The bottom trace (1002) is the user cable tension, and the top trace (1004) is the virtual fan speed. As shown in FIG. 10, the bottom trace (1002) accelerates the physical actuator and virtual fan up to time (1006), and then the user no longer moves with the virtual fan and disengages via the virtual clutch as the user is no longer moving faster than the virtual fan. The virtual fan speed increase slightly with remaining momentum until time (1008), then starts to decay, since the virtual fan is decreasing down the amount of load and the amount of load that is applied to the user is decreasing as well.

The user then reengages at time (1010), as in a normal rowing/skiing exercise movement, wherein the experienced inertial is different and/or "easier" because of the momentum of the virtual fan, while the clutch is engaged and while the actuator is moving faster than the virtual fan blades it is spinning, accelerating up with a higher load on the user, which in turn increases the virtual fan speed at time (1012). The cycle then returns as the user and/or clutch disengages and virtual fan decays.

As with the above examples of "E" mechanical inertia emulation and inward slack control, the torque controller is dynamically changing the moment of inertia to provide a different experienced inertia, but with the flywheel mode it is based on more than acceleration. The controller is also monitoring velocity of the virtual fan and actuator velocity, and thus the rate of acceleration and deceleration are different. In one embodiment, the state space model of the virtual/emulated flywheel comprises position, velocity, acceleration, and forces applied to it in order to update state through a timeline. The state space model also includes an emulated drag and/or fluid so that a viscous fluid for the fan may be emulated along with a fan in air. In one embodiment, a speed controller is used that if the user is pulling outwards faster than the virtual fan, the virtual clutch is engaged to allow the user to put energy into the motor and engage motor torque.

Thus, monitoring motor rotational position determines motor rotational velocity, which is translatable into a linear speed of cable/actuator due to gearing ratios. The clutch then addresses the question of whether the linear speed of the user pulling the cable is greater than the speed of the virtual/emulated flywheel. If it is greater, then the user applies a force to the virtual/emulated flywheel because it is moving faster than it. If a user is moving faster than the emulated flywheel, then the amount that the emulated flywheel accelerates proportional to the the amount of force that applies against a user, depending on a delta between the amount of force a user is contributing versus the emulated fan's moment of inertia.

Drop Set Mode.

In one embodiment, a digital strength training/exercise device may be more effective by permitting a mode using drop sets, a strength training technique to have a user perform a set until the user reaches a certain level of fatigue, then gradually reducing the weight without stopping until the user reaches failure. Physiological studies have shown that drop sets are time efficient and allow increased session training volume with minimal rest period, as maximal muscle growth has been shown to occur when a user is within two to three reps to failure.

In one embodiment, a drop set mode dynamically shifts the amount of applied load based on velocity inputs throughout the set, and trying to maintain that. A user is thus consistently at a "two to three reps to failure" state throughout a large part of the set.

In one embodiment, a performance metric to identify that a user is close to failure is the decay in mean concentric phase velocity. In one embodiment, the velocity during the concentric phase between 10% and 90% of the range of motion is averaged and compared to the maximal concentric phase velocity attained throughout the set. A decay condition is asserted at a threshold, for example 70% of the maximal concentric phase velocity.

In one embodiment, when the decay condition is asserted the "two to three reps to failure" state is enabled and the applied load to a user is decreased by a threshold, for example by seven or eight percent. These thresholds are dynamic based on movement and movement types and/or based on user profiles and user history. After the set is dropped a first time, the system looks for subsequent situations where the user is continuing to go slower than that value. If the next rep is faster, for example, no drop occurs, but once the mean concentric phase velocity is smaller than a threshold, for example 70% of the maximal for the new weight/applied load, the applied load to the user is again decreased.

Torque Controller Technique.

Torque that is requested of a motor is adjusted to generate an experienced inertia different from a mechanical inertia of an actuator, wherein the motor provides resistance to the actuator; and wherein the actuator is coupled to the motor.

In one embodiment, a cable acceleration of a cable coupled between the motor and the actuator is determined, and torque is adjusted based on the determined cable acceleration. In one embodiment, the experienced inertia is reduced to be less than the mechanical inertia at least in part by adjusting motor torque based on the determined cable acceleration. In one embodiment, during an acceleration portion of a concentric phase of a user exercise movement, the experienced inertia is reduced to be less than the mechanical inertia at least in part by reducing motor torque based on the determined cable acceleration. In one embodiment, during a deceleration portion of a concentric phase of a user exercise movement, the experienced inertia is reduced to be less than the mechanical inertia at least in part by increasing motor torque based on the determined cable acceleration.

In one embodiment, an inward slack event is detected, and in response to the detected inward slack event, the motor torque is incrementally increased until positive tension is detected of a cable coupled to the motor and the actuator. In one embodiment, the experienced inertia is increased to be more than the mechanical inertia at least in part by adjusting motor torque based on the determined cable acceleration. In one embodiment, during an acceleration portion of a concentric phase of a user exercise movement, the effective inertia experienced by the user is increased to be more than the mechanical inertia at least in part by increasing motor torque based on the determined cable acceleration. In one embodiment, during a deceleration portion of a concentric phase of a user exercise movement, the effective inertia experienced by the user is increased to be more than the mechanical inertia at least in part by reducing motor torque based on the determined cable acceleration.

In one embodiment, the mechanical inertia of the actuator comprises inertia due to fixed mass components within the exercise device. In one embodiment, the mechanical inertia of the actuator comprises inertia due to at least one of the following: a motor moment of inertia; a differential moment of inertia; an actuator inertia; a cable inertia; and a set of pulley inertia.

Physics of Virtual Ergometers.

As described by Anu Dudhia of Oxford University on Feb. 19, 2008, ergometers comprise: a flywheel, to store the energy between strokes and/or simulating the boat/skier momentum; an actuator/handle, attached to the flywheel via a chain and sprocket, or cable and pulley and/or simulating the oar/skier pole; a damping mechanism on the flywheel, to simulate water friction on the hull/snow friction on the skis; a return mechanism, to simulate motion of boat to front-stops/skiing motion; and a power/speed monitor. A virtual ergometer is referred to herein as any emulation of one or more of these components of an ergometer using a digital exercise machine using a motor, for example the motor (106) in FIG. 1A, for example with a virtual flywheel, referred to herein as an emulation of the flywheel in an ergometer using a digital exercise machine.

Using physics' laws of motion expressed in terms of angular velocity ω , which is the same for any point on the rotating body, is more convenient than linear velocity v . The two velocities are related by $\omega=v/r$ where mass m occurs in equations for translational systems, in rotational systems this is replaced by the moment of inertia, $I=\Sigma r^2dm$,

which is the summation of each component δm of the overall mass at each radius r . Angular momentum J is related by $J=I\omega$, and torque T is related by $T=d(I\omega)/dt=I(d\omega/dt)=I\cdot b$, where a constant moment of inertia is assumed for a rigid body and b is the angular acceleration. Work W is related by $W=T\cdot\theta$, and power P is related by $P=T\cdot\omega$, where θ is the rotation angle. Force and torque may remain constant during the work in which case $\int dW=J\cdot d\theta$.

Power Dissipation.

An ergometer flywheel and thus virtual flywheel loses speed primarily due to the energy required to 'pump' fluid, along with more minor friction on the bearings and fluid viscosity. Fluid is drawn into the system at a rate m/t [kg/sec] proportional to the flywheel speed ω , $m/t=a\cdot\omega$, where a is some constant dependent on the vent-settings, for example open vents=increased air flow for given rpm=larger value of a . This same fluid leaves the system with an outward velocity also proportional to the flywheel speed, so acquiring a kinetic energy proportional to the square of the flywheel speed. A mass m of fluid passing through the system therefore gains energy $E=\frac{1}{2}d m \omega^2$, where d is a constant for a given flywheel design. Thus, the flywheel is losing energy to the air at a rate/power dissipation proportional to the cube of the angular velocity $P=E/t=(E/m)(m/t)=k\cdot\omega^2$, where $k=\frac{1}{2}d\cdot a$ comprises the constants from the previous two relationships. This power dissipation appears as a drag torque D , proportional to the square of the angular velocity ω , $D=k\cdot\omega^2$.

Power Supplied.

An emulated ergometer operates in a translational system applying a force/and moving the actuator/handle with linear velocity v , producing power P , related by $P=F\cdot v$. The actuator/handle linear velocity is related to the angular velocity by the radius of the cog/pulley r of an ergometer flywheel and thus virtual flywheel, $v=\omega\cdot r$, wherein the virtual cog/pulley has an emulated radius for the virtual flywheel. The cog-size also determines the relationship between the applied force/ and the resulting torque T on the flywheel $T=F\cdot r$. If the flywheel rotates at a constant angular velocity, the applied torque T balances the average drag torque, $F\cdot r=k\cdot\omega^2$, thus the power P required from the rower is $P=F\cdot\omega\cdot r=k\cdot\omega^3$. Power is thus generally related to the cube of the flywheel speed, for example to make the flywheel rotate twice as fast, eight times as much power would need to be supplied.

Dampening.

For air-resistance ergs, damping may be controlled by sliding vents to restrict the amount of air that gets pumped by the fan, and in some cases the vent setting is controlled by a lever with ten positions. Changing the air flow into the physical erg translates to the constant a described above being altered. As the constant k is proportional to a , this changes the drag torque $D=k\cdot\omega^2$. If the same flywheel speed ω is to be maintained, the power required P_1 is then given by $P_1=k_1\omega^3$, or put another way $P_1=(k_1/k)P$ thus changing the damping alters the relationship between power and flywheel speed.

There are also other, unintentional, ways in which the damping can change which may also be emulated, such as: changes in friction in the bearings with age, proximity to a wall or other ergometers, fluid/air pressure, and fluid/air viscosity.

Measuring Dampening. During the recovery phase of an ergometer stroke cycle, no power is applied to the flywheel so it decelerates. During this period the only torque experienced by the flywheel is the damping, so representing Newton's 2nd Law, $D=-I(d\omega/dt)$. If the rate of change of angular velocity $d\omega/dt$, that is deceleration, is measured and

the moment of inertia I is known or presumed constant, and the same for all flywheels of the same/emulated model, the damping torque D may be calculated. As D itself is a function of angular velocity ω a more fundamental parameter is the drag factor k , related as $k=-I(d\omega/dt)(1/\omega^2)=Id(1/\omega)/dt$, where k may either be calculated rotation by rotation using the first expression and averaged, or just once for the whole recovery phase using the second expression. The calculated k may be displayed as units $10^{-6} \text{ N}\cdot\text{m}\cdot\text{s}^2$

By measuring the damping, the virtual ergometer may automatically compensate for any of the following: opening/closing vents to increase/reduce resistance; changes in friction on the flywheel bearings with time; and/or changes in air pressure, density, viscosity, and so on; environmental factors such as proximity to walls or other ergs. Further dampening may also be emulated separately, such as: changes in the chain friction; changes in the tension of the return mechanism; manufacturing variations in a flywheel with respects to moments of inertia; and/or changes in flywheel moments of inertia over time.

Measuring the Power Supplied.

With variable damping, the acceleration of the flywheel $d\omega/dr$ is measured during the stroke phase, and related to the net torque, as applied torque minus drag torque $T-D=I(d\omega/dt)$. The energy dE supplied by the rower to turn the flywheel through an angle $d\theta$ is therefore given by $dE=Td\theta=I(d\omega/dt)d\theta+Dd\theta=I(d\omega/dt)dt)d\theta+k\omega^2 d\theta$, where all the terms are either constant such as I , or may be directly measured on the digital exercise machine such as ω , t , and/or θ , or assumed constant from derivation during the previous recovery phase such as k . The average supplied power per stroke is then obtained by dividing the energy per stroke E by the time taken for each stroke cycle t , or $P=E/t$.

Overview of Flywheel Mode for Digital Exercise Machine.

For a digital exercise machine, such as that shown in FIG. 1A, a flywheel mode emulates the flywheel physics and simulated drag using the physics relationships described above for the virtual ergometer. Simulated drag, simulated dampener settings, and/or user modification affect resistance. Short and high intensity exercises may have a higher resistance, and slow and more endurance based exercise may have a lower resistance.

In one embodiment, there are more than 10 different movement patterns possible in flywheel mode, for example: classic skier mode, rope-based skiing, arm-based skiing, squat-to-row, and classic rowing mode. An advantage of flywheel mode on a digital exercise machine is the flexibility to convert any traditional strength training movement to an aerobic movement, for example a bench press movement may be easily converted to a bench press flywheel where each bench press on the concentric/outward direction engages a virtual flywheel with state space/memory and each eccentric/inward direction engages a clutch with much reduced resistance.

Thus in flywheel mode, on the outward direction the harder a user pulls, the more resistance that is generated, the faster the simulated flywheel spins, the less challenging the next repetition is—unless the user goes faster again. On the inward direction, a physical ergometer has a clutch which disengages the flywheel, turning it effectively into a bungee cord that springs in. A digital exercise machine may not have this functionality, so instead modifying an inward resistance profile is disclosed. Put another way, a user pulls out with a flywheel feel, and then a set of consistent eccentric or inward resistance profile is applied. Controlling slack, inertia, and momentum at the end ranges of motion is disclosed.

In one embodiment, inertial factors and impulse waves are applied to essentially modify and/or minimize the resistance, in part because a flywheel is heavy at the start of the range of motion and light at the end range of motion, creating higher amounts of inertia, momentum, and slack at the end range of motion. Predicting and/or identifying end of range motion slack and responding to slack appropriately is disclosed, in part to ease up slack and ease back to a steady speed.

In one embodiment, a user engaging in flywheel mode may be tracked with sensors, for example position and/or back EMF sensors in relation to the motor, and/or sensors that detect position and/or speed in relation to the cable. A user experience may be enhanced with reporting of output work, output force, output energy, and/or output power-both peak and average. Other reporting includes stroke rate, revolutions per minute, and/or distance traveled as calculated by the angular velocity and virtual state space. That is, distance traveled may increase even if the motor is not moving because a virtual flywheel state may indicate it continues to travel.

In one embodiment, coaching and form feedback for a user is provided using cues based on speed, position, distance, consistency or entropy of the movement pattern, smoothness of the movement pattern, and/or feedback around the body position of the individual. Coaching is provided directly to the user through the console, for example (208) of FIG. 2, or through a user's smart device like a phone or tablet. For example, coaching is provided to indicate proper bending of a user's knees, a user obtaining triple extension at the start of movement, and/or a user reaching the right depth at end of movement. Guided movement and/or coaching may be provided for any movement pattern possible in flywheel mode, for example skiing coaching or rowing coaching.

In one embodiment, safety protocols are used in flywheel mode. A parameter is used to set the maximum force that the digital exercise machine is allowed to output. For example, if a virtual flywheel is uncontained, exceptional users may be able to pull higher forces than the motor could generate and cause an emergency stop or overheating of the motor windings. In one embodiment, a maximum capacity is set for the unit at 125 pounds per arm or 250 pounds for the unit. Emulation of Flywheel by Motor.

A physical flywheel fan may have little mass and may be considered agile, light, and thin. By contrast, a motor has mass which in comparison is bigger and heavier than the flywheel fan. Furthermore, coupled components like a differential (B201) in FIG. 1B may add additional mass. Controlling the mass of the motor within a flywheel construct is disclosed, in part by using inertia control and/or slack detection. Put another way, an extra component not included in a virtual flywheel physics as described above is the motor and its mass. The motor being an active component is controlled to maintain the feel of a flywheel while minimizing the effects of its mass accelerating with inertia. Outward Inertia Handling.

In one embodiment, the mass of the motor and major components is used to determine, based on the speed and velocity and acceleration of the cable, its inertial contribution. An outward inertia factor as referred to herein is a multiplier to increase a threshold for slack detection. The outward inertia factor is used at the end of range of motion to provide a quicker, more aggressive slack detection.

In one embodiment, slack reduction is preemptively triggered before there is slack generated. In one embodiment, slack reduction is increased beyond the actual slack gener-

ated. Slack reduction preemptively triggered or over reduced is referred to herein as aggressive slack handling. In one embodiment, aggressive slack handling is triggered using the outward inertia factor.

5 For example, a user is using flywheel mode with a classic skier movement. With a skier at the end of range of motion, where the arms are coming into the chest, aggressive slack handling is used such that the harder the user pulls at this end of range of motion, more resistance is added. As the user 10 finishes the concentric/outward motion and begins to release their arms back in the eccentric/inward direction, an inward inertia handling is used.

Inward Inertia Handling.

In one embodiment, inward inertia handling increases the 15 slope of the amount of force added, when visualized as a horizontal axis as the actuator speed, and a vertical axis as the additional pounds of force added for inertial handling. Thus the faster a user moves near the end of motion, the more resistance is added via a pulse of duration and magnitude. The slope of the inward inertia handling force added is related to how much force is added and how long to apply the force via the pulse. The inward inertia handling force is determined as a function of how fast of an acceleration the 20 user is going near the end of motion.

25 Inward inertial handling enables an improved flywheel emulation. For example, if outward inertia handling is 100% theoretically perfect in removing all slack, it would change the resistance profile and appear to the user as the flywheel suddenly goes through a high viscosity fluid like mud at the 30 end of range of motion. Thus, outward inertia handling is aggressive at reducing slack but not perfect, and inward inertia handling continues slack reduction. A secondary reason for inward inertia handling is to increase velocity of the inward motion overall while the user relaxes and allows 35 inward motion for recovery of the aerobic cycle. Both slack reduction and user experience are improved with the inward inertia handling. For further example, if outward inertia handling is 0% and inward inertia handling is 100% theoretically perfect, a risk of a jerky user experience occurs 40 where a large inward pulse is required to absorb 100% slack that jerks the user actuator at the end of the large inward pulse.

FIG. 11A is a graphical illustration of a control loop for 45 flywheel mode slack control. Conceptually a graph is established in the controller (104) of FIG. 1A, wherein the x-axis represents time (1102) and a primary y-axis represents motor tension (1104) and a secondary y-axis represents actuator/cable tension (1106).

A user begins a flywheel mode cycle, for example and 50 without limitation in a classic skier movement at dotted line (1108) indicating the start of motion with the user's arms overhead. The user begins outward motion (1110) in part drawing their arms down until they reach the end of motion where the "skiing poles" are down (1112), reaching the 55 outward/inward motion crossover point. The user then recovers with inward motion (1114) by raising their arms up to the original position. For the user, the effort (1116) in terms of tension/force is during the first part of outward motion (1110) where they are driving the virtual flywheel.

60 In this same example, the motor tension observes the user force (1122) until nearing the end of motion at an outward position threshold (1124) where outward inertial handling (1126) is asserted as a first pulse. After the end of motion (1112) at the user's outward to inward crossover point 65 inward inertial handling (1128) is asserted as a second pulse, until an inward position threshold (1130) is reached. In one embodiment, the outward position threshold (1124) and

inward position threshold (1130) is between two to six inches from the end of motion (1112). Note in FIG. 11 that the outward inertial handling pulse (1126) and inward inertial handling pulse (1128) is not reflected in actuator/cable tension (1106) in part because of the slack in the cable.

In one embodiment, a “base weight” (1132) is referred to herein as a tension used to provide light resistance at any time a motor pulse (1122), (1126), (1128) is not asserted. In one embodiment, a base weight of seven pounds per side for two sides is used to provide a sensation similar to an ergometer. Note that the base weight may be asserted when speeds of the motor are differing, for example after pulse (1128) on the inward phase of motion, the motor may be already near a maximum 180 inch/second, after the pulse (1128) has increased speed of the motor, while the base weight is seven pounds per side. Put another way, second pulse (1128) allows the motor to get up to speed faster in the inward direction.

In one embodiment, the first rep of a flywheel mode movement is used to establish range of motion. In part to bootstrap inertia handling for this first rep without knowing a priori the range of motion, a default resistance profile is used based on the actuator speed.

As described above, an embodiment of the exercise device comprises a motor that provides resistance to an actuator and a torque controller configured to adjust torque that is requested of the motor to generate an experienced inertia different from a mechanical inertia of the actuator, wherein the experienced inertia is a flywheel inertia model. In one embodiment, adjusting torque on the motor comprises reducing slack on the cable within a slack compensation distance (1124) from an end of a range of motion (1112). In one embodiment, reducing slack comprises applying a slack impulse wave (1126) to the motor before the end of the range of motion (1112) is reached. In one embodiment, applying the slack impulse wave (1126) comprises applying motor force duration or magnitude in proportion to a speed of the actuator within the slack compensation distance (1124) from the end of the range of motion (1112) while the actuator is moving in an outward direction (1110). In one embodiment, the slack compensation distance (1124) is less than six inches from the end of the range of motion (1112).

In one embodiment, adjusting torque comprises reducing inertia or momentum for the motor within an inertia compensation distance (1130) from an end of a range of motion (1112) of a given exercise movement for the exercise device. In one embodiment, reducing inertia or momentum comprises applying an inertia impulse wave (1128) to the motor after the end of the range of motion (1112) is reached for a given exercise movement for the exercise device. In one embodiment, applying the inertia impulse wave (1128) comprises applying motor force duration or magnitude in proportion to a speed of the actuator recorded while the actuator is moving in an outward direction (1110). In one embodiment, the inertia compensation distance (1130) is less than six inches from the end of the range of motion (1112).

In one embodiment, adjusting torque comprises reducing torque to a base weight (1132) when the actuator is within a crossover distance (1131) from the end of the range of motion (1112). In one embodiment, the crossover distance (1131) is less than three inches from the end of the range of motion (1112) and the base weight (1132) is less than seven pounds.

Outward and Inward Pulse Determination.

In one embodiment, the magnitude and width of the outward inertial handling pulse (1126) and inward inertial handling pulse (1128) is determined dynamically for each flywheel mode cycle and/or rep.

The magnitude and width of the outward inertial handling pulse (1126) is determined based at least in part on slack detection which may include monitoring instantaneous speed and/or the virtual flywheel speed.

The magnitude of inward inertial handling pulse (1128) is determined based at least in part on the mean concentric velocity of the outward phase of the rep. That is, the faster the rep, the higher the magnitude of force (1128). In one embodiment, the width of the inward pulse (1128) is static. Social Flywheel Mode.

In one embodiment, movements in flywheel mode are used in a social mode with one or more other users also using their machines simultaneously or at a different time historically.

In a first example, a first user may race or score against a second user by traversing a course, say a rowing course. They may gain points by traversing the course at a given dampening/resistance factor, for example 20 points per knots rowed at dampening factor 2, but 40 points per knots rowed at dampening factor 3. The user may indicate by verbal or touch cue when they want to increase or decrease dampening factors.

In a second example, a first user may collaborate with a second user by rowing together virtually as single-person boats that draft or otherwise coordinate with each other.

When drafting a partner, the collaboration system adjusts dampening factors appropriately to mimic actual dynamics of streamlining through the water.

In a third example, a first user may collaborate with a second user by rowing together virtually as a two-person boat requiring synchronization of the rowing movement. The collaboration system may indicate with haptic cues, audio cues, or visual cues when synchronization between the first user's and second user's rowing stroke is improving or degrading.

In a fourth example, a first user may compete with a second user based on racing historically or locally significant venues such as an aquatic park nearby to a university campus or a historical Olympic course. The competition system can keep track of the speed/distance rowed to tell who wins the race. In one embodiment, a virtual reality headset is used to further immerse each user in the venue and a realistic avatar is used to represent the other user racing with considerations for time of day and weather conditions which may be reflected to a user with drag/dampening factor, along with haptic, audio, and visual cues.

In a fifth example, a first user may compete with a second user based on “quick starts” of multiple acceleration from standing still. Unlike a physical ergometer that has to slow down or physically interfere with the flywheel to stop, a virtual flywheel may be electronically reset. Thus, the competition system electronically resets the virtual flywheel in a series of quick starts between the users to see who is fastest in five sprints of a set distance or time.

As described above, an embodiment of the exercise device comprises a motor to that provides resistance to an actuator and a torque controller configured to adjust torque that is requested of the motor to generate an experienced inertia different from a mechanical inertia of the actuator, wherein the experienced inertia is a flywheel inertia model. In one embodiment, the flywheel inertia model comprises a state space model of an emulated flywheel, wherein the exercise device further comprises a processor configured to

use the state space model to determine a rotational speed of the emulated flywheel based at least in part on: tension of a cable coupled to the motor and the actuator; and velocity of the cable; and wherein the torque controller is further configured to adjust motor torque based at least in part on a comparison of a user velocity to the determined rotational speed of the emulated flywheel.

In one embodiment, the state space model of the emulated flywheel comprises an emulated resistance dampener to determine a drag factor for the emulated flywheel. In one embodiment, the state space model of the emulated flywheel comprises a social and/or gaming interface to determine a synchronization factor for the emulated flywheel based at least in part on information received from a second exercise machine. For example, the synchronization factor may be used in drafting a partner as described in the second example above, or in the synchronization of rowing movement as described in the third example above.

In one embodiment, the processor is further configured to present a guided content to a user of the exercise device during an exercise movement, for example for coaching skiing or rowing. In one embodiment, the processor is further configured to adjust the state space model of the emulated flywheel based at least on a drag factor for the emulated flywheel related to an emulated dynamic resistance damper and a coaching of the guided content. For example, a coach may encourage a user/rower that they are doing well, and suggest traversing into a (virtual) current for a better workout.

Chains Approach to Replace Pulsing for Flywheel Mode.

In one embodiment, instead of inward pulse (1128) a gradual approach is used, referred to herein as the “chains approach” as it starts heavier and ends up lighter like chains exercises with decreasing weights resistance. Thus, rather than having the second pulse (1128) entirely and/or using a smaller/less aggressive second pulse (1128), a faster/heavier resistance is used at the start of transition to inward motion, which becomes lighter, to give the same speed element to address slack. FIG. 11B is a graphical illustration of a control loop for flywheel mode slack control using the chains approach. FIG. 11B is identical conceptually to FIG. 11A, wherein the x-axis represents time (1102) and a primary y-axis represents motor tension (1104) and a secondary y-axis represents actuator/cable tension (1106), but illustrating the chains approach (1152) as replacing the inward pulse (1128).

In the example of FIG. 11B, a smooth curve approach (1152) is used to completely replace the inward pulse (1128), but other embodiments not shown in FIG. 11B may be used including: using a smaller/less aggressive inward pulse (1128) along with the chains (1152) curve and/or using a linear or other shaped chains (1152) approach. In one embodiment, as described above adjusting torque comprises adjusting inertia or momentum for the motor to emulate chains for the exercise device while the actuator is moving in an inward direction.

System Approach for Flywheel Mode.

Thus, a system for emulating a flywheel using a motor is disclosed, comprising: a motor that provides resistance to an actuator coupled to the motor via a cable; a processor configured to: use a state space model of an emulated flywheel to determine a rotational speed of the emulated flywheel based on tension of the cable and speed of the cable; and a torque controller configured to: adjust motor torque based on a comparison of a user speed to the determined rotational speed of the emulated flywheel. In one embodiment, adjusting torque comprises reducing inertia on

the cable within an inertia compensation distance from an end of a range of motion of a given exercise movement for the actuator.

FIG. 12 is a flow diagram illustrating an embodiment of a process for flywheel mode. In one embodiment, the system of FIG. 1A carries out the process of FIG. 12, for example in the torque controller (104) of FIG. 1A. In step (1202), torque that is requested of a motor, for example motor (106) of FIG. 1A, is adjusted to generate an experienced inertia different from a mechanical inertia of an actuator, for example actuator (110) of FIG. 1A, wherein the experienced inertia is a flywheel inertia model, wherein the motor that provides resistance to the actuator; and wherein the actuator is coupled to the motor.

15 Overview of Drop Set Mode for Digital Exercise Machine.

For a digital exercise machine, such as that shown in FIG. 1A, an improvement that is more efficient for a user's time is to use a drop set mode that involve drop sets, a strength training technique to have a user perform a set until the user reaches a certain level of fatigue, then gradually reducing the weight without stopping until the user reaches failure. Research literature and research evidence suggests that the reps closest to failure are more effective and contribute a large amount to muscle growth/hypertrophy. In one embodiment, any strength training movements typically used with a digital exercise machine may be used in a drop set mode, preferably movements that are not alternating between a left arm and a right arm.

One basic premise is for a set of ten reps with ten reps from failure and/or ten rep maximum (“10 RM”) weight, the eighth, ninth, and tenth reps are more hypertrophic than the first, second, and third reps. There has also been analysis suggesting a linear relationship between proximity to failure and the amount of muscle stimulus/growth/hypertrophy obtained.

In traditional strength training, for example in a gym with dumbbells, a scenario showing the user's time efficiency is as follows. In a drop set example in the gym with dumbbells, a user starts with their 10RM weight of a 25-pound dumbbell. The user lifts the 25-pound dumbbell ten times, gaining the benefit of the 8th, 9th, and 10th rep at 25-pounds. The user then takes between five to ten seconds to put down the 25-pound dumbbell and prepare a 20-pound dumbbell, which physiologically the user may be able to lift eight reps before failure/exhaustion. The user then takes between five to ten seconds to put down the 20-pound dumbbell and prepare a 15-pound dumbbell, which physiologically the user may be able to lift seven reps before failure/exhaustion. The user then takes between five to ten seconds to put down the 15-pound dumbbell and prepare a 10-pound dumbbell, which physiologically the user may be able to lift six reps before failure/exhaustion.

Research suggests in this traditional drop set example that the user doing four drop sets which may take about two minutes, is roughly equivalent to doing three straight sets of 25-pound dumbbells, which with a two-to-three minute break between sets would take about ten minutes. This is an improvement with a strong reduction in user's time exercising. Put another way, the same user could not reduce their two-to-three minute break between sets to ten seconds without increasing acidity in their muscle tissue, for example their calcium ions would be higher, pH acidity would be lower, and neuromuscular acetyl coenzyme would insist on down regulating motor unit recruiting, eventually causing pain and damage in a user's muscle tissue to reach the same user exercise time. The perception of effort is greater than can be sustained.

39

Drop set mode for a digital exercise device is disclosed. A digital exercise device is an example of a system for facilitating a drop set, comprising: a motor that provides resistance to an actuator coupled to the motor; and one or more processors configured to: monitor a velocity of a user when performing repetitions of an exercise movement; based at least in part on an evaluation of the monitored velocity, determine that the user is within a range of proximity away from failure; in response to determining that the user is within the range of proximity away from failure: dynamically adjust torque requested of the motor to drop resistance to maintain the user within the range of proximity away from failure.

A digital exercise device is an improvement over traditional strength training device for user convenience, efficiency and safety. As described above, drop sets are an improvement over traditional sets for user efficiency. Drop set mode for a digital exercise device is an improvement over drop sets for a traditional strength training device in at least four aspects: assessment of when to drop a weight in terms of failure estimation for a specific user; removal of the rest period between drop weights; and reducing the magnitude of weight differences for a given drop; and/or assessment of drop set termination.

Assessment of when to Drop.

Traditional self-assessment or coach-assessment of how many reps of a given movement for a given user at a given stage of training would result in failure may not be accurate. Coaching a user to perform a movement to the point of actual physical failure is manual, painful to a user, and may even injure a user. Determining the number of repetitions in reserve (RIR), referred to herein as the repetitions a user may perform before momentary failure, is thus an improvement to user efficiency, safety, and pain.

As referred to herein, momentary failure is when a user demonstrates visibly and/or significantly degraded performance. To illustrate the term momentary failure as referred to herein, imagine a hypothetical situation; a user is working out and a human trainer is observing them. The user is absolutely determined to do as many reps as possible, and unlike traditional training techniques the trainer wants them to stop only after they have reached their physical limit and their performance is visibly and significantly degraded. The user struggles, even slows at one point, but then seems to have resurgence and does more reps at a faster speed, completely mentally determined to keep going. Eventually their muscles start to give out and they cannot lift the weight up again, their speed and range of motion decreasing substantially. At that point, the trainer recognizes that further attempted reps are pointless because the only way the person can continue is by recruiting other muscles and sacrificing good form. This final point is momentary failure and the RIR=0.

Visible symptoms of a user reaching momentary failure include:

slowing down during a concentric phase, which may engage a spotter if slow enough;

speeding up during an eccentric phase, even dropping the actuator such as handles/bar/rope;

longer rests between reps or very long rests over an overall workout/set. For example, one rep after a huge rest may be ok, but not more, which may stop someone at that point at RIR=0. For example, a five second rest

40

or less may be a cutoff assuming they were going faster before;

range of motion reduction between reps;

sacrificing form, referred herein as “cheating”, to recruit other muscles like twisting the body on a single arm row;

There are prior factors and information that may slightly increase/decrease the probability of failure, which may be detected and or input:

10 Sleep length and/or sleep quality;

Muscle fatigue from using the same or similar muscle group earlier in a current workout;

Lack of stability and/or shaking limbs, for example a stabilizer giving out such as a user’s core giving out in a goblet squat may cause a “butt tuck” degradation. Another example during a bench press movement is when hands shake; and

Cardio and central nervous system (“CNS”) fatigue from doing a lot of volume and/or not resting much between sets, even when using different muscle groups.

To be explicit on what momentary failure is not, it is not mental failure. For example, it is possible a person ends a set because they think they cannot do another rep or just are not feeling like it, and that is not considered momentary failure by the definition herein. The final RIR result should be greater than zero in this case of mental failure. Similarly, maximum relative perceived exertion (“RPE”) is not failure, and RPE is not RIR. A user may state that a set was extremely difficult but if they were to actually push themselves to do more reps, it is possible they could have done more before physically failing. Finally, the point where a user traditionally should stop doing reps for an effective and safe workout is not momentary failure, and momentary failure generally involves more reps to get to RIR=0.

35 In traditional drop sets, a user and/or coach manually assesses failure, with a question on judgment of when to drop the weight in terms of future failure not only for the first drop but for subsequent second and third drops as well. Automating when to drop the weight for a given user is an 40 improvement to user consistency and may improve hypertrophy by more accurately estimating RIR and/or estimation to failure.

Concentric Speed.

In one embodiment, dynamically determining RIR and/or 45 estimation of failure is based on the concentric speed detected by the position/velocity of the motor sensor and/or actuator sensor. In the concentric phase, this is the speed that the user asserts in the first phase of the movement, for example pulling up on an arm curl. In one embodiment, 50 mean concentric velocity is the concentric velocity averaged over the entire concentric phase, which may be trimmed from the start and end of range of motion. In one embodiment, a threshold is used to determine when to begin a drop. For example, a first drop may occur when the digital 55 exercise machine identifies that the mean concentric velocity is at a 20% drop from the initial mean concentric velocity.

In one embodiment, mean concentric velocity is the 60 concentric velocity averaged over all similar users. That is, the digital exercise machine may be configured to share aggregated historical data across a network of digital exercise machines to use as a larger training data set for machine learning to establish mean concentric velocity for the same movement and for similar users. In one embodiment, the larger training data set includes labels for “spotter” sets where a user, coach, and/or exercise machine has determined a user needs spotting and thus is closer to failure. For example, given an initial concentric velocity for a given user

doing a bench press, a threshold of 20% of the mean concentric velocity averaged over all users with the same initial concentric velocity for bench press is used. This may also be referenced as a peak to 80% measure. As referred to herein, a similar user may be a user who shares at least one of the following: similar initial concentric velocity; similar performance in the exercise movement and/or related movements; similar physical attributes like age, sex, height, and/or weight; similar physiological attributes like slow twitch/fast twitch muscle composition, blood pressure, and/or VO₂ max; and/or similar demographics.

Waveform Detection.

In one embodiment, dynamically determining RIR and/or estimation of failure is based on the waveform detected by the position/velocity of the motor sensor and/or actuator sensor. As referred to herein, the waveform is the position/velocity waveform over time. That is, rather than a single value such as mean concentric velocity being used to determine when to start the first drop as described above, the entire concentric velocity versus time is graphed and compared to similar users using machine learning and/or other comparison methods to historical data across a network of digital exercise machines and users, which may be used as a larger training data set.

Power Training and other RIR Margins.

As described above, research indicates strong muscle hypertrophy happens when RIR is less than or equal to two. There is another discipline of power training for when RIR is greater than five. As referred to herein, power training is improving peak power theoretically by keeping resistance between 30% and 90% of maximum resistance depending on the type of movement so that training occurs when a user generate the most amount of power, wherein power is defined as force times velocity. One set principle in power training is specific adaptation to impose demand, and so a user trains power at higher power. Put another way, instead of increasing hypertrophy through fatigue, fatigue is considered negative for producing high amounts of force and velocity in power training.

Thus, in keeping with physiological mechanisms the weight is dropped not to keep a user in fatigue but instead to keep a user in peak power production and out of fatigue. A digital exercise machine, instead of detecting RIR<=2 and dropping based on this would detect RIR<=5 and keep the user in a “sweet spot”/zone of where their peak power is high.

Concentric and Eccentric Drop Sets.

Digital exercise machines with their finely controlled motors allow instantaneous changing of tension and/or perceived weight so as to also allow different weight within a set, for example the weight for a concentric/outward phase of a movement may be different from a weight for an eccentric/inward phase of a movement. In one embodiment, failure estimation may take into account failure within a set and/or differing concentric/eccentric weights. For example, a movement for drop set mode may have different concentric and eccentric tension which are each scaled with similar factors or with differing factors during each drop, depending on the movement. For example, estimation of failure may take into account a weighted blend of concentric velocity and eccentric velocity. For example, a movement for drop set mode may have a “half drop” set where the concentric tension is dropped for a set before the eccentric tension is dropped. For example, a dynamic weight mode of chains may be engaged wherein the weight changes over time

during the movement, which is also scaled during each drop. In one embodiment, the first rep for a dynamic weight mode is not applied.

Returning to the system approach, in one embodiment, the range of proximity away from failure comprises a number of repetitions away from failure. In one embodiment, a determination that a user is within the range of proximity away from failure is based on determining a decrease in velocity as compared to one or more previous repetitions. In one embodiment, the determination that the user is within the range of proximity away from failure is based on determining a decay in mean concentric phase velocity. In one embodiment, dropping of resistance is performed between a current repetition of the exercise movement and a next repetition of the exercise movement. In one embodiment, the dropping of resistance is performed at an end range of motion of the current repetition. In one embodiment, the dropping of resistance is performed between a concentric phase of the current repetition and an eccentric phase of a next repetition. In one embodiment, the one or more processors are further configured to terminate the drop set in response to identifying momentary failure. In one embodiment, the momentary failure is identified from the monitored velocity.

25 Removal of Drop Set Rest Period.

In traditional drop sets, after a drop has initiated, the user must put down the weight and pick up a new weight, by lifting a new free weight such as a dumbbell, rekeying a weight stack, and so on. Digital exercise machines may 30 eliminate this physical rest period by instantaneously changing weight and provide a continuous/fluid drop set. An improvement of the removal of the drop set rest period is that the user's time efficiency is further increased by, for example, making a two minute traditional drop set complete 35 within ninety seconds instead.

In one embodiment, the digital exercise machine cues the user when a weight is about to change and/or changes. For example, a digital exercise machine may render a concentric velocity on a machine display and/or mobile display that 40 shows a bar indicating the value of mean concentric velocity that shows green when it is higher than the 20% drop threshold, and grey when it is below the threshold. For example, a digital exercise machine may render an audio cue when the weight drops and/or utter the new weight when the weight drops. In one embodiment, a digital exercise machine 45 will give a user interface signal when there are no more drops, for example a user has reached four drops in twenty reps. Thus, the system may include an interface that provides information to the user pertaining to the drop set. In one embodiment, the information provided to the user comprises information pertaining to one or more of: the monitored velocity; a dropping of resistance; a cue to indicate occurrence of a resistance drop; a cue to indicate an amount of resistance drop; a termination of the drop set; or an indication 50 that no further drops in resistance will be performed.

Reducing the Drop Weight Differences.

In traditional drop sets, a drop weight difference may be a function of available free weights and/or cable stack plate sizes. For example, a user may find it socially awkward to 55 take all the available dumbbells on a gym rack during a busy period at the gym, and even then the dumbbells are only available every 5 lb, such as 10 lb, 15 lb, 20 lb, and so on. For example, a user may have a cable stack only available in 10 lb increments, such as 10 lb, 20 lb, 30 lb, and so on. 60 Digital exercise machines may provide an arbitrarily precise value of tension that does not take additional space or resources, for example, a digital exercise machine may be

set to 66 lb or even fractions of pounds such as 33.2 lb. An improvement of reducing drop weight differences is that arbitrary steps such as dumbbells and weight stacks may not correspond with a given user's physiology, and so using a digital exercise machine keeps the user closer in terms of weight to failure and thus closer to muscle hypertrophy, and more efficiently keeps the user closer to failure to make more efficient use of a user's time. Put another way, once the user is approximately two reps from failure, the subsequent drops may keep the user one-to-three reps from failure for the entire set from that point onwards. In one embodiment, instead of 10RM an eight rep maximum ("8RM") weight is used, as it makes the drop set more efficient in terms of a user reaching failure in the first set.

In one embodiment, the resistance is dropped by a percentage amount. In one embodiment, the amount of weight dropped is simplified to a static drop of 12% reduction for the first drop and 8% reduction for subsequent drops. In one embodiment, multiple drops in resistance are progressively performed throughout the drop set.

In one embodiment, an amount of reduction of resistance is dynamically adjustable for each drop. In one embodiment, the amount of weight dropped is dynamic based at least on a position and/or speed waveforms in comparison to larger training data sets for similar users. In one embodiment, a motor provides an initial resistance comprising a suggested maximum resistance for a number of repetitions. In one embodiment, the amount of resistance that is dropped is based on the initial resistance.

Drop Set Termination.

Determining when a user is done with the drop set is an important step with digital drop set mode, in that it may be possible to reach a drop weight that a user can maintain and never reach failure with, such as five pounds tension. In one embodiment, a drop set termination cap of twenty reps may be assessed so that after twenty reps the drop set terminates. In one embodiment, a drop set termination cap, for example twenty reps, is permitted when at least a threshold number of drops have occurred, for example four drops. In one embodiment, a permitted number of drops is capped.

In one embodiment, a drop set termination cap reduces a "forever set" wherein a user selects starting a drop set with too low a weight. This is an improvement in that it prevents a user from wasting their own time with too low a challenge in a drop set. In one embodiment, the digital exercise machine encourages a user to start with their 8RM weight.

Example of Drop Set Mode

A traditional drop set for a bench press may be a user starting with an 80 lb barbell which is the user's 10RM:

After eight sets of the 80 lb barbell, the user takes a fifteen second break to remove weights off the bar to 70 lb;
After five sets of the 70 lb barbell, the user takes a fifteen second break to remove weights off the bar to 60 lb;
After four sets of the 60 lb barbell, the user takes a fifteen second break to remove weights off the bar to 50 lb; and
After three sets of the 50 lb barbell, the user ends the drop set. In total, it has taken the user 20 sets and 45 seconds in break to complete the drop set, with 12 of the 20 sets in increased hypertrophy.

A digital exercise machine drop set mode for a bench press movement may be a user starting with a 70 lb tension which is the same user's 8RM:

After six sets of the 70 lb bench press, the digital exercise machine switches instantaneously to 64 lb;

After three sets of the 64 lb bench press, the digital exercise machine switches instantaneously to 59 lb;
After two sets of the 59 lb bench press, the digital exercise machine switches instantaneously to 55 lb;
After one set of the 55 lb bench press, the digital exercise machine switches instantaneously to 50 lb;
After one set of the 50 lb bench press, the digital exercise machine switches instantaneously to 46 lb;
After one set of the 46 lb bench press, the digital exercise machine switches instantaneously to 42 lb;
After two sets of the 42 lb bench press, the digital exercise machine switches instantaneously to 39 lb;
After two sets of the 39 lb bench press, the digital exercise machine switches instantaneously to 36 lb;
After two sets of the 36 lb bench press, the digital exercise machine switches instantaneously to 33 lb; and
After two sets of the 33 lb bench press, the user cannot lift another weight. In total, it has taken the user 22 sets with zero seconds in break to complete the drop set, with 20 of the 22 sets in increased hypertrophy. Thus this is an improvement over the traditional drop set in that it eliminates the need for 45 seconds break time, and keeps the user closer to failure with 20 sets in increased hypertrophy instead of 12 sets in increased hypertrophy.

FIG. 13 is a flow diagram illustrating an embodiment of a process for drop set mode. In one embodiment, the system of FIG. 1A carries out the process of FIG. 13, for example in the torque controller (104) of FIG. 1A. In step (1302), a velocity of a user when performing repetitions of an exercise movement on an actuator, for example actuator (110) of FIG. 1A, is monitored. In step (1304), based at least in part on an evaluation of the monitored velocity, it is determined that the user is within a range of proximity away from failure. In step (1306), in response to determining that the user is within the range of proximity away from failure: torque requested of a motor, for example motor (106) of FIG. 1A is dynamically adjusted to drop resistance to maintain the user within the range of proximity away from failure, wherein the motor provides resistance to the actuator; and wherein the actuator is coupled to the motor.

In one embodiment, the dropping of resistance is performed between a current repetition of the exercise movement and a next repetition of the exercise movement. In one embodiment, multiple drops in resistance are progressively performed throughout the drop set.

Although the foregoing embodiments have been described in some detail for purposes of clarity of understanding, the invention is not limited to the details provided.

50 There are many alternative ways of implementing the invention. The disclosed embodiments are illustrative and not restrictive.

What is claimed is:

1. An exercise device, comprising:
a motor that provides resistance to an actuator coupled to the motor; and
a torque controller configured to:
adjust torque that is requested of the motor to generate an experienced inertia different from a mechanical inertia of the actuator, wherein the experienced inertia is a flywheel inertia model, wherein the flywheel inertia model comprises a state space model of an emulated flywheel; wherein the exercise device further comprises a processor configured to use the state space model to determine a rotational speed of the emulated flywheel based at least in part on: tension of a cable coupled to the motor and the actuator; and velocity of

the cable; and wherein the torque controller is further configured to adjust motor torque based at least in part on a comparison of the velocity of the cable to the determined rotational speed of the emulated flywheel, wherein adjusting torque comprises reducing inertia or momentum for the motor within an inertia compensation distance from an end of a range of motion of a given exercise movement for the exercise device.

2. The exercise device of claim 1, wherein adjusting torque comprises reducing slack on a cable within a slack compensation distance from the end of the range of motion of the given exercise movement for the exercise device, wherein the cable is coupled between the motor and the actuator.

3. The exercise device of claim 2, wherein reducing slack comprises applying a slack impulse wave to the motor before the end of the range of motion is reached for the given exercise movement for the exercise device.

4. The exercise device of claim 3, wherein applying the slack impulse wave comprises applying motor force duration or magnitude in proportion to a speed of the actuator within the slack compensation distance from the end of the range of motion while the actuator is moving in an outward direction.

5. The exercise device of claim 4, wherein the slack compensation distance is less than six inches from the end of the range of motion.

6. The exercise device of claim 1, wherein reducing inertia or momentum comprises applying an inertia impulse wave to the motor after the end of the range of motion is reached for the given exercise movement for the exercise device.

7. The exercise device of claim 6, wherein applying the inertia impulse wave comprises applying motor force duration or magnitude in proportion to a speed of the actuator recorded while the actuator is moving in an outward direction.

8. The exercise device of claim 7, wherein the inertia compensation distance is less than six inches from the end of the range of motion.

9. The exercise device of claim 1, wherein adjusting torque comprises reducing torque to a base weight when the actuator is within a crossover distance from the end of the range of motion.

10. The exercise device of claim 9, wherein the crossover distance is less than three inches from the end of the range of motion and the base weight is less than seven pounds.

11. The exercise device of claim 1, wherein the processor is further configured to present a guided content to a user of the exercise device during an exercise movement.

12. The exercise device of claim 11, wherein the processor is further configured to adjust the state space model of the emulated flywheel based at least on a drag factor for the emulated flywheel related to an emulated dynamic resistance damper and a coaching of the guided content.

13. The exercise device of claim 1, wherein the exercise device further comprises a storage device configured to store a range of motion of the actuator for a first repetition of an exercise movement for a user.

14. The exercise device of claim 1, wherein the state space model of the emulated flywheel comprises an emulated resistance dampener to determine a drag factor for the emulated flywheel.

15. The exercise device of claim 1, wherein the state space model of the emulated flywheel comprises a gaming interface to determine a synchronization factor for the emulated flywheel based at least in part on information received from a second exercise machine.

16. The exercise device of claim 1, wherein adjusting torque comprises adjusting inertia or momentum for the motor to emulate chains for the exercise device while the actuator is moving in an inward direction.

17. A system for emulating a flywheel using a motor, comprising:

the motor that provides resistance to an actuator coupled to the motor via a cable;

a processor configured to:

use a state space model of an emulated flywheel to determine a rotational speed of the emulated flywheel based on tension of the cable and speed of the cable; and

a torque controller configured to:

adjust motor torque based on a comparison of the speed of the cable to the determined rotational speed of the emulated flywheel,

wherein adjusting motor torque comprises reducing inertia or momentum for the motor within an inertia compensation distance from an end of a range of motion of a given exercise movement for the actuator.

18. A method, comprising:

adjusting torque that is requested of a motor to generate an experienced inertia different from a mechanical inertia of an actuator, wherein the experienced inertia is a flywheel inertia model; wherein the flywheel inertia model comprises a state space model of an emulated flywheel; wherein the exercise device further comprises a processor configured to use the state space model to determine a rotational speed of the emulated flywheel based at least in part on: tension of a cable coupled to the motor and the actuator; and velocity of the cable; and wherein the torque controller is further configured to adjust motor torque based at least in part on a comparison of the velocity of the cable to the determined rotational speed of the emulated flywheel, wherein adjusting torque comprises reducing inertia or momentum for the motor within an inertia compensation distance from an end of a range of motion of a given exercise movement for the actuator; wherein the motor provides resistance to the actuator; and wherein the actuator is coupled to the motor.
